(57) **ABSTRACT**

A skate riser as described herein can include adjustable offset capability or static offset capability. In the case of risers with static offset capability, presented herein are various skate riser systems that generally have a skate riser defined between a boot adapter mount end and a skate runner mount end, wherein the skate riser is not adjustable. The skate riser system further comprises a boot adapter mount that is connected to the boot adapter mount end. The boot adapter mount is configured to connect to a boot sole of a skate boot. A quick release shaft extends into a riser aperture in the riser between the ends. The quick release shaft comprises a key that retains a skate runner mount to the riser when in a first position/orientation but not when in a second position/orientation. Advantages of the static offset skate riser includes the ability to quickly swap out a blade with one configuration with a blade having a different configuration or simply just swapping out a blade.

MODULAR SKATE RISER

**CROSS-REFERENCE TO RELATED
APPLICATIONS**

This application is a Continuation-in-Part Application which claims priority to and the benefit of U.S. patent application Ser. No. 18/074,604 entitled Fore/Aft Dove Tail Adjustable Hockey Runner Assembly filed on Dec. 5, 2022, which is a Continuation Patent Application claiming priority to and the benefit of U.S. patent application Ser. No. 17/500,876 entitled Adjustable Hockey Runner Assembly filed on Oct. 13, 2021, which is a Divisional Patent application claiming priority to U.S. Non-Provisional patent application Ser. No. 16/581,133 entitled Adjustable Hockey Runner Assembly filed on Sep. 24, 2019, the entire disclosure of which is hereby incorporated by reference.

BACKGROUND OF THE INVENTION

1. Field of the Invention

The present invention relates generally to an ice-skate riser assembly.

2. Description of Related Art

A fundamental interest in the human experience is sport. We will spend our wealth and resources on whatever sport/s piques our interest vying for the latest innovation that could possibly give us a competitive edge. The progression of sport innovations is easily recognized by sports equipment related filings over the years at the United States Patent and Trademark Office. In the field of hockey for example, hockey skates are generally comprised of a boot and steel blade bolted or fixed to the boot sole. Modern hockey skates typically include innovations such as a hard plastic shell that accepts a portion of the skate blade whereby the shell is bolted to the skate blade and may further act as an interface and attachment medium to the boot sole. With that the, the current state of hockey skate technology leaves open lots of problems yet to be solved in the march for the best hockey skate for a given purpose defined by the game.

It is to innovations related to improving hockey blades and runners that the subject matter disclosed herein is generally directed.

SUMMARY OF THE INVENTION

The present invention generally relates to a quick release riser arrangement that connects an ice-skate to an ice-skating boot.

Accordingly, certain embodiments contemplate a skate riser system comprising a riser defined between a boot adapter mount end and a skate runner mount end, wherein the riser is not adjustable. The skate riser system further comprises a boot adapter mount that is connected to the boot adapter mount end. The boot adapter mount is configured to connect to a boot sole of a skate boot. A quick release shaft extends into a riser aperture in the riser between the ends. The quick release shaft comprises a key that retains a skate runner mount to the riser when in a first position/orientation but not when in a second position/orientation.

Yet another embodiment of the present invention envisions a skate riser and quick release apparatus comprising a static riser having a boot adapter mount configured to attach to a boot sole, and a skate runner mount that extends from

2

a skate runner. The skate runner mount can be removably connected to the static riser via a quick release shaft that extends through the skate runner mount and at least a portion of the static riser.

5 Another embodiment of the present invention contemplates a method for disengaging a skate runner from a skate boot. The method is to a riser that comprises a boot adapter mount configured to attach to a boot sole at one end and a skate runner mount at the other end. The skate runner mount extends from a skate runner. One step is for engaging a retaining extension that extends from the skate runner mount in an overlapping relationship with the riser, wherein when in the overlapping relationship a runner mount retaining channel of the retaining extension aligns with a riser channel of the riser. Another step is a step for locking the retaining extension to the riser via a quick release shaft that extends through the riser channel and the runner mount retaining channel.

20 **BRIEF DESCRIPTION OF THE DRAWINGS**

FIGS. 1A-1B illustratively shows a side view and an orthogonal view of a blade runner with a serrated top in accordance with an embodiment of the present invention;

25 FIG. 1C depicts an enlarged image of a serrated top locking mechanism in accordance with an embodiment of the present invention;

FIG. 1D depicts a front view of a blade runner with a 30 serrated top in accordance with an embodiment of the present invention;

35 FIGS. 1E and 1F illustratively depict line drawings of several other profile embodiments of a skate runner cross-section consistent with embodiments of the present invention;

FIG. 1G illustratively depicts yet another embodiment of a 40 skate runner consistent with embodiments of the present invention;

FIGS. 1H and 1I illustratively depict another embodiment 45 of a skate runner consistent with embodiments of the present invention;

FIGS. 2A-2C illustratively depict line drawings of a 50 skate runner blade coupled with an over mold core consistent with embodiments of the present invention;

FIGS. 3A-3D illustratively depict line drawings of a 55 skate runner blade and overmold core coupled with a skate overmold consistent with embodiments of the present invention;

FIGS. 4A and 4B illustratively depict a line drawing of a 60 standalone rib and backbone interlocking mount embodiment consistent with embodiments of the present invention;

FIGS. 4C-4E illustratively depict line drawings of mounting plates with interlocking mounts consistent with embodiments of the present invention;

FIGS. 5A-5D illustratively depict line drawings of various 65 views of mounting plate embodiments attached to the front and back mounting surfaces consistent with embodiments of the present invention;

FIGS. 6A-6E are line drawings 70 illustratively depict an overview of a multi-degree of freedom adjustment arrangement consistent with embodiments of the present invention;

FIG. 6F illustratively depicts the skate assembly connected with an ice-skate boot consistent with embodiments of the present invention;

FIGS. 7A-7G 75 illustratively depict line drawings of a pronate/supinate platform embodiment consistent with embodiments of the present invention;

FIGS. 7H-7J are line drawings that illustratively depict of digital pronate/supinate platforms with individual fore/aft dovetail placement configurations consistent with embodiments of the present invention;

FIGS. 8A-8D illustratively depict line drawings of a bi-directional locking dovetail module embodiment in a neutral position consistent with embodiments of the present invention;

FIGS. 8E-8G illustratively depict line drawings of the bi-directional locking dovetail module 700 adjusted enough front (fore) position consistent with embodiments of the present invention;

FIG. 8H-8J illustratively depict line drawings of the bi-directional locking dovetail module 700 adjusted enough back (aft) position consistent with embodiments of the present invention;

FIG. 8K illustratively depicts a front view line drawing of an alternate quick release embodiment consistent with embodiments of the present invention;

FIGS. 9A-9E illustratively depict line drawings of a side/side dovetail module embodiment engaged with a bi-directional locking dovetail module in a neutral position consistent with embodiments of the invention;

FIGS. 9F-9H illustratively depict line drawings of the side/side locking dovetail module adjusted to the far right position consistent with embodiments of the present invention;

FIGS. 9I and 9J show the side/side centerline pointer indicating that the side/side locking dovetail module is moved to the far right and far left, respectively;

FIGS. 10A-10F illustratively depicts line drawings of a lift ring embodiment cooperating with the side/side locking dovetail module 800 consistent with embodiments of the present invention;

FIGS. 10G and 10H illustratively depict different views line drawing of the lift ring in a raised vertical position consistent with embodiments of the present invention;

FIGS. 11A-11G illustratively depict line drawings of digital lift ring embodiments consistent with embodiments of the present invention;

FIGS. 12A-12E illustratively depicts line drawings of a protective cup embodiment that protects the front and rear multi-degree of freedom arrangements 660 and 670 consistent with embodiments of the present invention;

FIGS. 13A-13K are various line drawing views of an optional skate riser system embodiment consistent with embodiments of the present invention;

FIGS. 14A-14C are line drawings of various views of a side offset skate riser system consistent with embodiments of the present invention;

FIGS. 15A-15D are line drawings illustratively depicting various views of a side offset and fore/aft offset skate riser system consistent with embodiments of the present invention;

FIGS. 16A and 16B are line drawings of an optional embodiments of a riser system with varied riser heights (Z-heights) consistent with embodiments of the present invention; and

FIGS. 17A-17D depict optional skate runner mounts used with a blade and boot illustrating the combination of various offsets mounted to a skate.

DETAILED DESCRIPTION

Initially, this disclosure is by way of example only, not by limitation. Thus, although the instrumentalities described herein are for the convenience of explanation, shown and

described with respect to exemplary embodiments, it will be appreciated that the principles herein may be applied equally in other similar configurations involving the subject matter directed to the field of the invention. The phrases “in one embodiment”, “according to one embodiment”, and the like, generally mean the particular feature, structure, or characteristic following the phrase, is included in at least one embodiment of the present invention and may be included in more than one embodiment of the present invention. Importantly, such phrases do not necessarily refer to the same embodiment. If the specification states a component or feature “may”, “can”, “could”, or “might” be included or have a characteristic, that particular component or feature is not required to be included or have the characteristic. As used herein, the terms “having”, “have”, “including” and “include” are considered open language and are synonymous with the term “comprising”. Furthermore, as used herein, the term “essentially” is meant to stress that a characteristic of something is to be interpreted within acceptable tolerance margins known to those skilled in the art in keeping with typical normal world tolerance, which is analogous with “more or less.” For example, essentially flat, essentially straight, essentially on time, etc. all indicate that these characteristics are not capable of being perfect within the sense of their limits. Accordingly, if there is no specific $\pm$ value assigned to “essentially”, then assume essentially means to be within $\pm 2.5\%$ of exact. The term “connected to” as used herein is to be interpreted as a first element physically linked or attached to a second element and not as a “means for attaching” as in a “means plus function”. In fact, unless a term expressly uses “means for” followed by the gerund form of a verb, that term shall not be interpreted under 35 U.S.C. § 112(f). In what follows, similar or identical structures may be identified using identical callouts.

With respect to the drawings, it is noted that the figures are not necessarily drawn to scale and are diagrammatic in nature to illustrate features of interest. Descriptive terminology such as, for example, upper/lower, top/bottom, horizontal/vertical, left/right and the like, may be adopted with respect to the various views or conventions provided in the figures as generally understood by an onlooker for purposes of enhancing the reader's understanding and is in no way intended to be limiting. All embodiments described herein are submitted to be operational irrespective of any overall physical orientation unless specifically described otherwise, such as elements that rely on gravity to operate, for example.

Described herein are various multi-degree of freedom ice-skate risers with a quick release system that connects an ice-skate blade to the sole of an ice-skating boot generally which provides advantages of multiple degrees of freedom between the ice-skate blade and the ice-skating boot. Certain embodiments comprise a plurality of various offset risers that include a pronate/supinate platform, a bi-directional module and a side/side module. In some configurations, the pronate/supinate platform is connected with the ice-skate blade and is configured to move the ice-skate blade in a pronate and supinate direction. In some configurations the pronate supinate platform is connected with the bi-directional module providing offsets of the ice-skate blade in the fore and aft position.

Referring to the drawings in general, and more specifically to FIGS. 1A-1D, shown therein is an illustration of a skate/blade runner embodiment constructed in accordance with an embodiment of the present invention. In what follows, similar or identical structures may be identified using identical callouts.

FIGS. 1A-1D illustratively depict a skate runner 100 defined by an elongated skate runner body 103 that spans between a front end 190 and a rear end 192 and has a blade height 111 that extends between a bottom region 104 in the top region 118. As shown in conjunction with FIG. 1D, the bottom region 104 defines a bottom width 128 and the top region 118 defines a top width 126 that terminates at a top surface 102. A blade edge 101, which in the present embodiment is concave, is adapted to contact an ice sheet (not shown). The blade edge 101 is located at the distal edge of the bottom region 104. In the present embodiment, the bottom width 128 is wider than the top width 126, which provides a weight reduction. The top region 118 joins the bottom region 104 by way of a stress relieving radius 110. The stress relieving radius 110 inhibits crack formation between the top region 118 and the bottom region 104. Certain embodiments envision the stress relieving radius 110 having a circular curvature. The present embodiment envisions a unitary skate runner 100 made up of stainless steel. Other embodiments envision skate runner made of different materials, such as titanium for example. In the present embodiment, the skate runner 100 has a leading rounded front edge 106 located in the front blade region 109 and trailing rounded rear edge 108 located in a rear blade region 107. Between the front edge 106 and the rear edge 108 is a slightly arced middle region 105. Certain embodiments envision the skate height 111 being between 0.75-2.5 inches, the bottom width 128 being between $\frac{1}{16}$ inches and $\frac{3}{16}$ inches and the top width 126 being between $\frac{1}{32}$ inches and $\frac{1}{8}$ inches. Other certain embodiments envision the bottom region 104 having a height that is one-half of the top region 118. Yet other embodiments envision the top region 118 being approximately $\frac{1}{3}$ of the overall skate height 111. The front blade region 109, the arced middle blade region 105, and the rear blade region 107 define the overall length 195 of the skate runner 100.

The present embodiment depicts a plurality of serrated protrusions 114 that extend along the top region 118 of the skate runner body 103 to provide a means for fixedly attaching an overmold to the top region 118 also shown by the isometric view of the skate runner 100 in FIG. 1B. As will be discussed infra, certain embodiments envision a skate runner essentially encapsulated by an overmold in the top region 118. The overmold mechanically locks to the top region 118 by infiltrating between the semicircles or other shapes in the top region 118. In this way, these adhesion features 114 provide enhanced shear strength. In the present embodiment, the serrated protrusions 114 are one of many different shapes that can accomplish the task of mechanically locking the top region 118 to an overmold. With special attention FIG. 1A, a single serrated protrusion 114 (of the many serrated protrusions) in the Circle-A is magnified in FIG. 1C. As shown in FIG. 1C, there is a bulbous end 112 at the tip of the single serrated protrusion 114 to improve adhering the overmold with the tip region 118.

FIGS. 1E and 1F illustratively depict line drawings of several other profile embodiments of a skate runner cross-section consistent with embodiments of the present invention. With reference to FIG. 1E, a skate runner 150 possesses a skate runner body 116 that is essentially a uniform width, which in certain embodiments can have overmold adhesion features such as holes/perforations, countersinks, counterbores, serrations, undercuts extending into the top region 118 or other shear strength enhancing arrangements, (see FIG. 1F). FIG. 1F depicts an optional skate runner embodiment 160 that illustratively shows a thinner top region 118 to accommodate a reduced weight runner blade with a lip

120 that runs at least along a portion of the top edge of the top region to lock the blade's upper region to an overmold. Though embodiments of the present invention envision a top region devoid of adhesion features within overmold, such a configuration may have adhesion disadvantages.

FIG. 1G illustratively depicts yet another embodiment of a skate runner consistent with embodiments of the present invention. As shown, the skate runner 130 possesses a smooth top edge 134 with a narrower width in the top region 118 as compared to the lower/bottom region 104. The skate runner 130 possesses circular perforations 132 that pass through the top portion 118 to create anchor points for an overmold. Though eight pass-through holes 132 are shown, there can be more or less without departing from the scope and spirit of the present invention. Certain embodiments envision different shaped perforations and in different orientations while maintaining functionality consistent with that of the present invention. Though the skate runner blade 130 possesses perforated holes 132, other embodiments 15 20 25 30 35 40 45 50 55 60 65 70 75 80 85 90 95 100 105 110 115 120 125 130 135 140 145 150 155 160 165 170 175 FIGS. 3A-3D illustratively depict line drawings of a skate runner blade and overmold core coupled with a skate overmold 300 consistent with embodiments of the present invention. FIG. 3A is an isometric line drawing of the skate runner blade 100 and overmold core 200 that is essentially encased by the skate overmold 300. As shown, the skate overmold 300 essentially runs the length of the skate runner 100 from the front end 190 to the rear end 192 leaving the blade portion 104 exposed/uncovered. In the present embodiment, the skate overmold 300 comprises a front mounting surface 302 and a rear mounting surface 304.

FIG. 3B illustratively depicts a top view line drawing of the skate overmold 300 wherein the front mounting surface 302 and the rear mounting surface 304 are essentially planar with the page. The mounting surfaces 302 and 304 are configured to attach the skate runner 100 and overmold 300 either directly or indirectly to the sole 680 of an ice-skating boot 699. Specifically, each of the mounting surfaces 302 and 304 possesses a female interlocking mount sleeve/receptacle 306, which in this embodiment is at least one circular hole 307 and a female slot and rib arrangement 322 adapted to receive a male counterpart, discussed later. The mounting surfaces 302 and 304 can be a unitary part of the skate overmold 300 or optionally fittings that attach or are molded into the skate overmold 300. In the present embodiment, the skate overmold 300 comprises a center seam 320 where two halves of the skate overmold 300 are compressed together wedging the overmold core 200 there between, while other embodiments envision the skate overmold 300 formed of a unitary piece of material. Some embodiments envision the mounting surfaces 302 and 304 being formed from the same material as the skate overmold 300, while other embodiments envision the mounting surfaces 302 and 304 formed out of a different material than the skate case that 300, such as metal or carbon composite for example.

FIG. 3C illustratively depicts a side view line drawing of the skate runner 100 and overmold 300 with a cross-section line A-A passing through the rear mounting surface 304.

FIG. 3D illustratively depicts a cross-section line drawing along cross-section line B-B. As shown, the skate overmold 300 is defined by a sidewall 308 that extends between a blade/overmold (blade to overmold) interface 312 and an overmold top surface 310, which in this perspective is the rear mounting surface 304. Certain embodiments envision the skate overmold 300 being comprised of a different material than the overmold core 200 to create a material mismatch thereby reducing vibrational effects caused by relative motion at the interface 179 of the blade edge 101 with an ice sheet 177. In the present embodiment, it is easily seen that the skate overmold 300 completely encases the overmold core 200, however other embodiments are not so limiting. For reference, a neutral plane 315 is defined in the Z' direction along a central axis 314, that is centrally located, in the bottom width 128 in the vertical direction 123 and essentially along the blade length 195 in the X' as shown by the vertically hashed plane 315.

FIGS. 4A and 4B illustratively depict a line drawing of a standalone rib and backbone interlocking mount embodiment consistent with embodiments of the present invention. FIG. 4A shows a bottom perspective line drawing view of a standalone interlocking mount 400A with ribs 401 dispersed along a spine 404 between two cylindrical ends 402A. The cylindrical ends 402A comprise threaded through-holes 432 configured to receive threaded bolts (not shown). The standalone interlocking mount 400A cooperates with one of the matching sleeves/receptacles 306 wherein the bottom standalone mount surface 406A interfaces the bottom of the

sleeve/receptacle 306. In other words, the standalone interlocking mounts 400A fit into the sleeve 306 like puzzle pieces, as can appreciated by the identical male and female geometries 400A and 306. The interlocking mounts 400A can be fixedly attached into the cooperating sleeves 306 (such as by glue, adhesive, mechanically attached or by other methods known to those skilled in the art). FIG. 4B illustratively shows a top view of the standalone interlocking mount 400A wherein certain embodiments envision the top surface 434 being flush with the mounting surface 302 or 304.

Though not limited to the rib 401 and spine 404 configuration, the present configuration provides distributed load and stiffness as well as additional adhesive contact area when affixed to the overmold. The standalone interlocking mounts 400A provide support for a digital adjusting system discussed later.

FIGS. 4C-4E illustratively depict line drawings of mounting plate embodiments with interlocking mounts consistent with embodiments of the present invention. As shown in FIG. 4C, the interlocking mounts 400B is more or less identical to 400A except that the interlocking mount 400B extend from the bottom mounting plate surface 418 of the mounting plate 405. Similar parts of 400 are denoted herein as 'A' and 'B' because though they are different elements they are configured similarly as will be appreciated in the description and figures. Each of the interlocking mounts 400B are configured to cooperate with a matching sleeve/receptacle 306 wherein the bottom standalone mount surface 406B interfaces the bottom of the sleeve/receptacle 306. The identical but opposite male and female geometries 400B and 306 closely conform to one another. The interlocking mounts 400B can be fixedly attached into the cooperating sleeves 306 (such as by glue, adhesive, mechanically attached or by other methods known to those skilled in the art). Certain embodiments envision the mounting plate 405 and the male interlocking mount 400B being of unitary construction. Certain other embodiments envision the mounting plate 405 and the male interlocking mount 400B being made out of metal, polymer, nylon, carbon composite, glass filled, or other materials known to those skilled in the art.

FIG. 4D illustratively depicts a line drawing top view of a mounting plate embodiment of FIG. 4C consistent with embodiments of the present invention. The mounting plate 405 comprises an arced top surface 414 that in some embodiments tracks a portion of a cylinder as shown. The cylinder segment 405 is defined as arcing around a contact axis 650 (see FIG. 6A). The rocker high point 113 of the blade edge 101 defines the contact axis 650 when the blade edge 101 is in the neutral plane 315. The mounting plate 405 possesses two bolt receiving tapped holes 412 adapted to receive threaded bolts (not shown here). The mounting plate 405 is defined by a front surface 410 and a back surface 411, whereby certain embodiments envision pronate/supinate graduated indicia 416 visibly disposed on at least the front surface 410. FIG. 4E illustratively depicts a line drawing of the front surface 410 of the mounting plate 405 showing the pronate/supinate graduated indicia 416. Certain other embodiments envision the pronate/supinate graduated indicia 416 comprising numbers, degrees, or other reference markings. In the present embodiment, the bottom mounting plate surface 418 is flat and interfaces/mates to one of the flat mounting surfaces 302 for 304. Certain other embodiments contemplate the bottom mounting plate surface 418 further adhering to the mounting surface 302 or 304. Other embodiments envision the bottom mounting plate surface 418 and

the interlocking mount 400B being removably connected to a mounting surface 302 or 304.

FIGS. 5A-5D illustratively depict line drawings of various views of mounting plate embodiments attached to the front and back mounting surfaces consistent with embodiments of the present invention. FIG. 5A shows a top view line drawing of a mounting plate 405 connected with a front mounting surface 302 and a mounting plate 405 connected with a rear mounting surface 304. FIG. 5B illustratively shows a side view line drawing of front mounting surface 302 and rear mounting surface 304 each connected with a mounting plate 405. A cross-section line A-A passing through the rear mounting surface 304 and mounting plate 405 is shown. FIG. 5C illustratively depicts a line drawing isometric view of mounting plates 405 connected with the front mounting surface 302 and the rear mounting surface 304. FIG. 5D illustratively shows a cross-section view of the relationship of the skate runner 100, the overmold core 200, the skate overmold 300 and the mounting plate 405 connected to the rear mounting surface 304. In the present embodiment, the aforementioned components 100, 200, 300, and 405 are symmetric in regards with the neutral plane 315. Also shown is one of the bolt receiving tapped holes 412 in the mounting plate 405 that is adapted and configured to receive a threaded bolt (not shown here).

FIGS. 6A-6E are line drawings illustratively depict an overview of a multi-degree of freedom adjustment post arrangement consistent with embodiments of the present invention. A post is optionally referred to herein as a riser. FIG. 6A illustratively depicts a side view line drawing of a skate assembly 690 that includes the skate runner 100 and skate overmold 300 with front and rear multi-degree of freedom arrangements 660 and 670. The front and rear multi-degree of freedom arrangements 660 and 670 essentially take the place of a static ice-skate post that connects a skate blade to a skate boot sole 680. Hence, the front and rear multi-degree of freedom arrangements 660 and 670 can also be considered front and rear multi-degree of freedom skate posts 660 and 670. As shown in FIG. 6A, the front multi-degree of freedom arrangement 660 is adjustably connected with the front mounting surface 302 and mounting plate 405 and can be moved in the X₁ direction. The rear multi-degree of freedom arrangement 670 is adjustably connected with the rear mounting surface 304 and mounting plate 405 and can be moved in the X₂ direction. The X₁ and X₂ directions are synonymously used herein with the terminology 'fore' and 'aft' directions. The front multi-degree of freedom arrangement 660 attaches to the ice-skating boot front end 698 at front attachment plate 665. The rear multi-degree of freedom arrangement 670 attaches to the ice-skating boot rear end 696 at rear attachment plate 675. Certain embodiments contemplate the front and rear attachment plates 665 and 675 being convex to conform to the shape of lift rings 900 (as shown in FIG. 10A). Also as shown, the rocker high point 113 of the blade edge 101 defines the contact axis 650 when the blade edge 101 is in the neutral plane 315 (such as when the blade edge 101 is in contact with a sheet of ice 177).

The front and rear multi-degree of freedom arrangements 660 and 670 each possess a bi-directional locking module 700A and 700B, respectively discussed in more detail in conjunction with FIG. 8A-8J. Because the bi-directional locking modules 700A and 700B are responsible for the X₁ and X₂ directions, certain embodiments envision disengaging the skate runner 100 and skate overmold 300 with front and rear multi-degree of freedom arrangements 660 and 670 when the bi-directional locking modules 700A and 700B are loosened. When the front and rear multi-degree of freedom

arrangement 660 and 670 are attached to the sole 680 of an ice-skate boot 699, disengaging the skate runner 100 and skate overmold 300 front and rear multi-degree of freedom arrangements 660 and 670 effectively disengages the skate runner 100 and skate overmold 300 from the ice-skate boot 699. This can facilitate swapping out a different skate runner 100 and skate overmold 300 quickly and easily. A different skate runner 100 and skate overmold 300 can include a longer blade, a thinner blade, a more flexible blade, a different material blade, a sharpened blade, etc.

FIG. 6B illustratively depicts a line drawing of a front view of the skate assembly 690 embodiment with the front multi-degree of freedom arrangement 660 consistent with embodiments of the present invention. Here, the front multi-degree of freedom arrangement 660 is adjustable in the Z₁ directions, also referred to herein as up and down directions and a angular rotation, and the positive and negative direction as indicated by the two-way arrow also referred to herein as pronate/supinate angle.

FIG. 6C illustratively depicts a line drawing of a rear view of the skate assembly 690 embodiment with the rear multi-degree of freedom arrangement 670 consistent with embodiments of the present invention. Here, the rear multi-degree of freedom arrangement 670 is adjustable in the Z₂ directions, and a angular rotation and the positive and negative direction as indicated by the two-way arrow.

FIG. 6D illustratively depicts a top view line drawing of the skate assembly 690 embodiment consistent with embodiments of the present invention. As shown here, the front multi-degree of freedom arrangement 660 can be made to move in a side to side direction Y₁ as shown, also referred to herein as 'side/side', and an angular rotation ϕ_1 in the same plane as the side direction Y₁. Similarly, the rear multi-degree of freedom arrangement 670 can be made to move in a side to side direction Y₂ as shown, and an angular rotation ϕ_2 in the same plane as the side direction Y₂. Hence, the front multi-degree of freedom arrangement 660 can be made to move in at least the Y₁, X₁, ϕ_1 , α directions and the rear multi-degree of freedom arrangement 670 can be made to move in at least the Y₂, X₂, ϕ_2 , α directions. As will be appreciated based on the present description, the skate runner 100 can be moved with respect/relative to the boot sole 680 independently (from a different degree of freedom) in each degree of freedom. In other words, one adjustment direction is not required to be dependent on a different adjustment direction.

With reference to the top portion of the front multi-degree of freedom arrangement 660, the front attachment plate 665 is shown cooperating with an elongated washer 668 that slidably fits in an even longer elongated washer recess 666. The front attachment plate 665, elongated washer 668 can be fixedly locked into position via a threaded top bolt 672. For purposes of description, a threaded bolt possesses a threaded bolt shaft and bolt head all of which are uniformly described under the element a threaded bolt, which in this case is the threaded bolt 672 but is not limited in this disclosure to the threaded bolt 672. In certain embodiments, the threaded top bolt head 672 is inside of a boot sole 680 thereby locking the front attachment plate 665, elongated washer 668 and fixedly attaching the front multi-degree of freedom arrangement 660 to the outside of the boot sole 680. In other words, the top bolt 672 can be used to fixedly attach the front multi-degree of freedom arrangement 660 to the outside of an ice-skating boot sole 680. Likewise, top portion of the rear multi-degree of freedom arrangement 670, the front attachment plate 675 is shown cooperating with an elongated washer 668 that slidably fits in an even longer

elongated washer recess 666. The rear attachment plate 675, elongated washer 668 can be fixedly locked into position via a threaded top bolt 672. The threaded top bolt head 672 can fixedly attach the rear attachment plate 675, elongated washer 668 and the rear multi-degree of freedom arrangement 670 to the outside of the boot sole 680. Accordingly, the two the top bolts 672 can be used to fixedly attached the front multi-degree of freedom arrangement 660 and the rear multi-degree of freedom arrangement 670 to the outside of an ice-skating boot sole 680.

FIG. 6E illustratively depicts an isometric line drawing of the skate assembly 690 that includes the skate runner 100 and skate overmold 300 built up with front and rear multi-degree of freedom arrangements 660 and 670. As shown, the front multi-degree of freedom arrangement 660 is shown built up with the front attachment plate 665 cooperating with the elongated washer 668 that slidably fits in the even longer elongated washer recess 666. As can be more easily seen from this vantage, the front attachment plate 665, elongated washer 668 can be fixedly locked into position via a threaded top bolt 672. Likewise, as shown, the rear multi-degree of freedom arrangement 670 is shown built up with the rear attachment plate 675 cooperating with the elongated washer 668 that slidably fits in the even longer elongated washer recess 666 all fixedly held in place with the threaded bolt head 672 pulling/compressing all the components into compression.

FIG. 6F illustratively depicts the skate assembly 690 connected with an ice-skate boot 699 consistent with embodiments of the present invention. As depicted, the threaded bolts 672 connect the ice-skate boot sole 680 to the front and rear multi-degree of freedom arrangements 660 and 670 at the front and rear attachment plates 665 and 675, respectively.

FIGS. 7A-7G illustratively depict line drawings of a pronate/supinate platform embodiment consistent with embodiments of the present invention. FIG. 7A is an isometric line drawing of a pronate/supinate platform 600 that is adjustably connected/attached to a mounting plate 405. The geometry of the platform bottom surface 609 matches the convex arc cylindrical segment 414 of the mounting plate 405 to rotate left and right in a sliding manner about the cylindrical segment 414. In other words, the platform bottom surface 609 is a concave arc that can rock angularly side by side about the convex arc cylinder segment 414 of the mounting plate 405 when in contact (in a mating/cooperating relationship). As also shown in FIG. 7B, pronate/supinate platform 600 has a pair of rectangular square nut cages 608, one at the platform front 634 and one at the platform rear 632. The square nut cages 608 are recesses that essentially trap a square nut 604 from turning when tightened down when screwed into place via a threaded bolt 602, as shown. The bottom of each square nut cage 608 has a slotted hole 604 for the threaded bolt 602 to go through, see FIG. 7F. The threaded bolt 602 engages and screws into a respective tapped hole 412 in the mounting plate 405, which in some embodiments are the two cylindrical threaded ends 402B on the underside 418 of the mounting plate 405 (see FIG. 4C). In this way, the pronate/supinate platform 600 can rock angularly side by side in a sliding fashion about the cylindrical segment 414. The threaded bolts 602 can lock the pronate/supinate platform 600 in a desired position when tightened.

FIGS. 7C-7E illustratively depict pronate and supinate motion of the pronate/supinate platform 600 relative to the mounting plate 405 consistent with embodiments of the present invention. In FIG. 7C, the pronate/supinate platform

600 is in a neutral position 640 (0° offset) on the mounting plate 405. When in the neutral position 640, a pronate/supinate centerline pointer 611 is in the center graduated indicium 416A of the pronate/supinate graduated indicia 416 indicating to an onlooker of the neutral position. The threaded bolt 602 can be tightened in each respective tapped hole 412 thereby compressing and rigidly fixing the pronate/supinate platform 600 and the mounting plate 405 together. Certain embodiments contemplate interlocking features at the convex and concave arced interface 414 and 609 to assist in locking the pronate/supinate platform 600 and the mounting plate 405 together. To move or otherwise adjust the pronate/supinate platform 600 to either be in a pronation position 635 or a supination position 645, a user needs to loosen each respective the threaded bolt 602 and move the pronate/supinate platform 600 to a desired position along the pronate/supinate graduated indicia 616. Once in the desired position the threaded bolt 602 can be tightened down to clamp the pronate/supinate platform 600 and the mounting plate 405 together. The front profile of the fore/aft male interlocking slide mount, which in this embodiment is a dovetail 606 is shown here and as shown in other figures, extends towards the fore/aft dovetail top 613 of the pronate/supinate platform 600. The male interlocking slide mount is configured to engage a female interlocking slide mount receptacle, such as a dovetail channel. As shown in FIG. 7A, the fore/aft dovetail 606 also extends longitudinally parallel to the contact axis 650 along the pronate/supinate platform top surface 613, which is to the concave arc 609 obverse (i.e., on the other side of the pronate/supinate platform 600). The fore/aft graduated indicia 616 are visibly disposed on at least one pronate/supinate platform side surface 619 along the side of the fore/aft dovetail 606. In the present embodiment, the fore/aft graduated indicia 616 have a centerline that is longer than the other fore/aft graduated indicia 616 to mark the neutral fore/aft position. Embodiments of the present invention commonly use a dovetail and channel configuration as an example of a male interlocking slide mount and female interlocking slide mount receptacle whereby optional structures can be used without departing from the scope and spirit of the present invention are envisioned and obvious with the benefit of understanding the present invention. Optional structures can include elements such as spheres in a channel, round profile bars in a channel, other shaped bars (different from a dovetail) and compatible channel, or other shaped male and female parts that accomplish the same motion while maintaining the same functionality within the scope and spirit of the present invention.

FIG. 7D shows the pronate/supinate platform 600 in a pronation position 635 on the mounting plate 405. In this far pronation position 635, the pronate/supinate centerline pointer 611 is pointing to the far right graduated indicium 416B of the pronate/supinate graduated indicia 416. The threaded bolt 602 can be tightened in the respective tapped hole 412 thereby compressing and rigidly fixing the pronate/supinate platform 600 and the mounting plate 405 together in the desired pronation position 635. Accordingly, the fore/aft dovetail 606 and all other elements extending upward from the fore/aft dovetail 606 are fixed/set in the pronation position 635 based on the desired pronation setting, which is easily determined via the pronate/supinate centerline pointer 611 and the desired graduated indicium 416. Likewise, as shown in FIG. 7E by loosening the threaded bolt 602, the pronate/supinate platform 600 can be moved to a supination position 645 on the mounting plate 405 and then fixed in position by retightening the threaded bolt 602. In this far left supination position 645, the pronate/

supinate centerline pointer 611 is in the far left graduated indicium 416C of the pronate/supinate graduated indicia 416.

FIG. 7F illustratively depicts a top view line drawing of the pronate/supinate platform embodiment 600 adjusted to a different angular position on the mounting plate 405. As shown, the square nuts 604 are shifted to the far side of the square nut cages 608 thereby changing the position of the fore/aft dovetail 606 in either a supinated or a pronated position, depending on your point of reference (i.e., if this is a right skate runner or a left skate runner, for example). As discussed earlier, each square nut cage 608 is essentially a recess with a bolt slot 604 that accommodates the shaft of the bolt 602 to pass-through the square nut cage floor 619, as shown. The bolt slots 604 allow the sliding movement of the pronate/supinate platform 600 over the arced mounting plate 405 when the two elements 600 and 405 are loosely connected together by the loosened but still engaged bolts 602. The square nuts 604 cooperating with the square nut cages 608 allow for an infinite number of positions within the rectangular length of each square nut cages 608. In the present embodiment, the pronate/supinate positions can be $\pm 4^\circ$, however other angular ranges, such as between $\pm 10^\circ$, or other, are envisioned within the scope and spirit of the present invention. As should be appreciated, when the threaded bolts 602 are tightened down, the bolt head 602 effectively compresses the square nut 604 into the square nut cage floor 619 fixedly clamping the pronate/supinate platform 600 to the mounting plate 405. As described earlier in conjunction with FIG. 4C, the threaded bolts 602 screw into the two cylindrical threaded ends 402B on the underside 418 of the mounting plate 405. When compressed, the frictional forces between these elements 602, 604, 619, 600 and 405 dominate holding these elements 602, 604, 619, 600 and 405 tightly together in a fixed manner.

FIG. 7G illustratively depicts a side view line drawing of the pronate/supinate platform embodiment consistent with embodiments of the present invention. As shown, the pronate/supinate platform 600 sits on top of the mounting plate 405 with the fore/aft graduated indicia 616 visibly displayed just underneath the fore/aft dovetail 606. When in view of FIGS. 6A-6E, it should be appreciated that the skate blade and runner 100/300 will effectively be angled in a desired pronate/supinate angle relative to an ice-skating boot sole 680 when the pronate/supinate platform 600 is adjusted with respect to the mounting plate 405.

Certain embodiments envision the pronate/supinate platform 600 not having the dovetail 606, but rather extending directly into the ice-skating boot sole 680. This would effectively restrict the degree of freedom for the ice-skate (boot 699 and skate blade 100) to the pronation and supination directions a.

FIG. 7H are top view line drawings that illustratively depict different digital angled pronate/supinate platforms with nonadjustable fore/aft dovetail configurations consistent with embodiments of the present invention. Unlike the adjustable pronate/supinate platform 600, each digital pronate/supinate platform 651 has a fixed offset for the fore/aft dovetail measured in degrees. As shown here, there are a) a 0° (neutral) pronate/supinate positioned fore/aft dovetail 648; b) a 1° pronate/supinate positioned fore/aft dovetail 652; c) a 2° pronate/supinate positioned fore/aft dovetail 654; d) a 3° pronate/supinate positioned fore/aft dovetail 656; and e) a 4° pronate/supinate positioned fore/aft dovetail 658 (even though $0-4$ deg are shown, larger angles and different angles are envisioned). There are two platform through-holes 671 spaced at either end of each digital

pronate/supinate platform 651 to align and attach to the threaded through-holes 432 in cylinders 402A of the stand-alone interlocking mount 400A. In this embodiment, there is no need for the mounting plate 405 or the other elements to facilitate pronate/supinate adjustability within a single system. Rather, this embodiment employs multiple single digital elements to accomplish altering the pronation and supination angle. Advantages of the standalone interlocking mount 400A and the digital pronate/supinate platforms 651 includes weight reduction and simpler parts. A disadvantage is freedom to adjust supination and pronation within a single system 405 and 600.

FIG. 7I illustratively depict front view line drawings of the digital pronate/supinate platforms 651 of FIG. 7H consistent with embodiments of the present invention. As shown, each of the fore/aft dovetails 648, 652, 654, 656, and 658 are shifted in degrees on the digital platform base 659. Certain embodiments envision the digital pronate/supinate platform 651 being constructed from a unitary piece of material, such as metal, polymer, nylon, carbon fiber composite, glass filled composite, or other materials known to those skilled in the art having functions applicable to that within the scope and spirit of the present invention. While other embodiments envision the digital pronate/supinate platforms 651 being comprised of multiple parts with common or optionally different materials. When in view of FIGS. 6A-6E, it should be appreciated that the skate blade and runner 100/300 will effectively be angled in a desired pronate/supinate angle relative to an ice-skating boot sole 680 with each digital pronate/supinate platform 651 (648, 652, 654, 656, and 658) employed with the standalone interlocking mount 400A.

FIG. 7J illustratively depict isometric line drawings of the digital pronate/supinate platforms 651 as shown in FIGS. 7H and 7I. In this embodiment, each fore/aft digital dovetail 648, 652, 654, 656, and 658 possesses fore/aft graduated indicia 616 visibly displayed just underneath the respective fore/aft dovetail 648, 652, 654, 656, and 658. The digital fore/aft digital dovetails 648, 652, 654, 656, and 658 are envisioned to seamlessly cooperate with a bi-directional locking dovetail module 700 discussed below in conjunction with FIGS. 8A-8D.

Certain embodiments envision the digital pronate/supinate platforms 651 not having the dovetails (648, 652, 654, 656, and 658), but rather extending directly into the ice-skating boot sole 680. This would effectively restrict the degree of freedom for the ice-skate (boot 699 and skate blade 100) to the incremental pronation and supination directions a.

FIGS. 8A-8D illustratively depict line drawings of a bi-directional locking dovetail module embodiment in a neutral position consistent with embodiments of the present invention. FIG. 8A in view of FIG. 8B illustratively depicts an isometric line drawing of a bi-directional locking dovetail module 700 coupled with (i.e., engaged in a cooperating relationship) a pronate/supinate platform 600 in a neutral position with respect to the connected mounting plate 405. Though not shown here, other certain embodiments contemplate the bi-directional locking dovetail module 700 coupled with a digital pronate/supinate platform 651 without any modification. With continued reference to FIGS. 8A and 8B, the bi-directional locking dovetail module 700 includes a threaded cylinder 702 with a fore/aft dovetail channel 708 on the bottom side 714 of the threaded cylinder 702. The bi-directional locking dovetail module 700 further includes a side by side, or side/side, dovetail channel 724 extending from the top side 716 of the threaded cylinder 702. The

side/side dovetail channel 724 is approximately 90° offset from the fore/aft dovetail channel 708. The fore/aft dovetail channel 708 is shown engaged with the fore/aft dovetail 606 on the pronate/supinate platform 600 in a female to male relationship. As mentioned, the side/side dovetail channel 724 runs, or otherwise extends, approximately 90 degrees from the fore/aft dovetail 606, facilitating side by side motion of a mating side/side dovetail 804, further described in FIGS. 9A-9J. The side/side dovetail channel 724 is defined by a pair of upper wedged shaped walls 710. Likewise, a pair of lower wedged shaped walls 706 defines the fore/aft dovetail channel 708. As depicted, a lower threaded ring 720 is cooperatively engaged with the threaded cylinder 702. As the lower threaded ring 720 is tightened against the fore/aft dovetail top 613 of the pronate/supinate platform 600, the bi-directional locking dovetail module 700 becomes locked in a desired fore/aft position by way of contact compression between the fore/aft dovetail 606 and the side walls 706 that comprise the fore/aft dovetail channel 708. In other words, the fore/aft dovetail 606 and the fore/aft dovetail channel 706 are frictionally held/constrained together when mated under compression. Certain embodiments envision the lower threaded ring 720 tightened by a human hand, but optionally could be tightened with a tool, such as a wrench (not shown). In some embodiments, the lower threaded ring 720 possesses grips 722 to assist in tightening down or loosening up the lower threaded ring 720 from engagement with the fore/aft dovetail top 613. Accordingly, in this embodiment the bi-directional module 700 can be adjusted in a desired fore or aft position by sliding the fore/aft dovetail 606 inside of the fore/aft dovetail channel 706 when the lower threaded ring 720 is not tightened down against the fore/aft dovetail top 613.

FIG. 8B illustratively depicts a front view line drawing of the bi-directional locking dovetail module 700 consistent with embodiments of the present invention. In this figure, the fore/aft dovetail channel 708 is engaged with the fore/aft dovetail 606 on the pronate/supinate platform 600 in a female to male relationship. As the lower threaded ring 720 is twisted downwards along the cylinder threads 701 against the fore/aft dovetail top 613, the pair of lower wedged shaped walls 706, that form the fore/aft dovetail channel 708, pull against the fore/aft dovetail 606. This creates a contact compression which effectively locks the opposing dovetail components 706 and 606 together so that they are frictionally constrained in place, i.e., in the desired locked position. Also shown here is a side/side centerline pointer 712, which is located on the outside of at least one of the lower wedged shaped walls 706 (which in some embodiments are on both the outer portion 713 of the lower wedge shaped walls 706) for improved viewing by an onlooker.

FIG. 8C illustratively depicts a top view line drawing of the bi-directional locking dovetail module 700 engaged with the pronate/supinate platform 600 in a neutral position with respect to the connected mounting plate 405 consistent with embodiments of the present invention. FIG. 8D illustratively depicts a side view line drawing of the bi-directional locking dovetail module 700 engaged with the pronate/supinate platform 600 in a neutral position consistent with embodiments of the present invention. The neutral position is indicated by the fore/aft centerline 711 lining up with the center fore/aft graduated indicium 616A.

FIGS. 8E-8G illustratively depict line drawings of the bi-directional locking dovetail module 700 adjusted in a front (fore) position consistent with embodiments of the present invention. FIG. 8E is an isometric view of the bi-directional locking dovetail module 700 moved/adjusted

all the way forward on the pronate/supinate platform 600. As discussed previously, the lower threaded ring 720 can be loosened to facilitate easy movement of the fore/aft dovetail channel 706 sliding over the fore/aft dovetail 606. Once in a desired forward position, the lower threaded ring 720 can be tightened to compress against the fore/aft dovetail top 613 thereby effectively locking the fore/aft dovetail 606 against the fore/aft dovetail channel 706 in position. In the present embodiment, there is no stop on either end of the fore/aft dovetail 606 facilitating a quick release of the skate runner 300 and blade 100 if the bi-directional locking module 700 is moved beyond engagement with the pronate/supinate platform 600. In other words, the fore/aft dovetail channel 706 is simply slid away from the fore/aft dovetail 606 causing the bi-directional locking module 700 to disengage with the pronate/supinate platform 600. When both of the front and the rear bi-directional locking modules 700A and 700B (see FIGS. 6A and 6E) are disengaged with their respective pronate/supinate platforms 600 the skate blade and runner 100/300 will effectively disengage with the ice-skate boot 699 that is connected to the front and rear multi-degree of freedom arrangements 660 and 670. This creates a “quick release” method of removing the runner from the boot.

FIG. 8F shows a side view line drawing of the bi-directional locking dovetail module 700 adjusted in the front position as indicated by the fore/aft centerline 711 lining up with the far right fore/aft graduated indicium 616B. FIG. 8G depicts a top view of the bi-directional locking dovetail module 700 engaged with the pronate/supinate platform 600 in the front position with respect to the connected mounting plate 405. When both of the front and the rear bi-directional locking modules 700A and 700B are moved together in a forward position, the skate blade and runner module 100/300 is effectively adjusted forward, accommodating a skater's desired fore/aft blade 100/300 position.

FIGS. 8H-8J illustratively depict line drawings of the bi-directional locking dovetail module 700 adjusted enough back (aft) position consistent with embodiments of the present invention. FIG. 8H is an isometric view of the bi-directional locking dovetail module 700 moved/adjusted all the way back on the pronate/supinate platform 600. FIG. 8F shows a side view line drawing of the bi-directional locking dovetail module 700 adjusted in the back position as indicated (for the benefit of an onlooker) by the fore/aft centerline 711 lining up with the far right fore/aft graduated indicium 616C. FIG. 8G shows a top view of the bi-directional locking dovetail module 700 engaged with the pronate/supinate platform 600 in the back/rear position with respect to the connected mounting plate 405. When both of the front and the rear bi-directional locking modules 700A and 700B are moved together in a back position, the skate blade and runner module 100/300 is effectively adjusted backwards, accommodating a skater's fore/aft skate blade 100/300 position. In the present embodiment, there is no stop on the back of the fore/aft dovetail 606, which enables/allows for the quick release of the skate blade and runner 100/300 when the bi-directional locking module 700 is loosened and in some embodiments is disengaged with the pronate/supinate platform 600. As previously mentioned, when both of the front and the rear bi-directional locking modules 700A and 700B (see FIGS. 6A and 6E) are disengaged with their respective pronate/supinate platforms 600, the skate blade and runner 100/300 will also effectively be disengaged with the ice-skate boot 699. The ice-skate boot 699 being connected to the front and rear multi-degree of freedom arrangements 660 and 670.

An optional embodiment envisions a modified bi-directional locking dovetail module **700** engaged with the pronate/supinate platform **600** or digital pronate/supinate platforms **651** at one end, but not having the side/side channel **724** or related hardware. Rather, the optional embodiment of the modified bi-directional locking dovetail module is envision to extend and attach directly into the ice-skating boot sole **680**. This would effectively restrict the degree of freedom for the ice-skate (boot **699** and skate blade **100**) to the supination directions a and the fore and aft directions X_1 and X_2 . It should be appreciated that when any of the elements are locked into place, those locked elements essentially become a rigid skate post. Hence, if the bi-directional locking dovetail module **700** is locked onto the pronate/supinate platform **600**, the two elements **600** and **700** functionally resemble a rigid post element. If the side/side locking dovetail module **800** is not locked down but the two elements **600** and **700** are locked down it is the equivalent of having a rigid post that only provides side-by-side motion.

FIG. 8K illustratively depicts a front view line drawing of an alternate quick release embodiment consistent with embodiments of the present invention. It should be clear that each degree of freedom described herein (e.g., Y_1 , X_1 , Z_1 , ϕ_1 , α) can be employed independently in a modified post arrangement particular to a specific degree of freedom. It should also be clear that more than one degree of freedom described herein, but less than all degrees of freedom described herein can be employed as desired in yet a different particular post arrangement. FIG. 8K is an example of a modified post arrangement particular to the specific degree of freedom X_1 or X_2 .

FIG. 8K shows one such embodiment where there is a single moving part in post arrangement **735**. In the present post arrangement **735** embodiment, the standalone male interlocking mount **400A** is bonded or otherwise fixedly attached into the skate overmold **300**. The digital platform base **659** of a digital neutral angled fore/aft dovetail **648** is fixedly connected to the male interlocking mount **400A** via a pair of threaded bolts (not shown). More specifically, the threaded bolts (not shown) are fixedly engaged with the threaded through-holes **432** in the pair of standalone threaded cylinders **402A** by way of the two platform through-holes **671** on either side of the digital platform base **659**. The digital neutral angled fore/aft dovetail **648** (used in this example) cooperates with the fore/aft dovetail channel **708** located at the bottom part of the modified fore/aft post arrangement **739**. The modified fore/aft post arrangement **739** possesses a threaded cylinder **702** at the bottom of the post **737** with a cooperating threaded ring **720** that can lock the fore/aft dovetail and channel **748** and **708** together, as previously described. The post **737** connects directly to an ice-skate boot sole **680**, as shown. When the threaded ring **720** is loosened, the skate blade and runner **100/300** disengages with the modified fore/aft post arrangement **739**. One can appreciate that different digital fore/aft dovetails **652**, **654**, **656**, and **658** or some other attachment means to the skate blade and runner **100/300** can be used without departing from the scope and spirit of this embodiment.

FIGS. 9A-9E illustratively depict line drawings of a side/side dovetail module embodiment engaged with a bi-directional locking dovetail module **700** in a neutral position consistent with embodiments of the invention. FIG. 9A in view of FIG. 9B shows a side/side dovetail locking module **800** connected to a bi-directional locking dovetail module **700** by way of a side/side dovetail **804** matingly engaged with the side/side dovetail channel **724**. The side/side dove-

tail module **800** generally comprises a side/side dovetail **804** that extends from a bottom side **814** of a threaded cylinder **802**. In the present embodiment, screw threads **801** run concentrically along the length of the threaded cylinder **802** from the threaded cylinder top **816** to the threaded cylinder bottom **814**, however other embodiments envision the threads **801** not extending to the threaded cylinder top **816** or bottom **814**. A plate **826** located at the threaded cylinder bottom **814** at least partially extends beyond the diameter of the threaded cylinder **802**, which in the present embodiment is not fully circular to allow human fingers to access a middle threaded ring **740**. Certain embodiments envision the plate **826** defined as a circular plate with two parts of the circle removed along parallel cuts **821**. The side/side dovetail **804** extends in a downward direction from the plate bottom **825**, as shown. There is at least one lift ring orientation recess **818** that can be a flat, a channel (as shown in the present embodiment), or some other kind of orientation recess that accomplishes a similar function within the scope and spirit of the present invention. The present embodiment depicts two lift ring orientation recesses **818** configured to engage a lift ring **900**, discussed below. Running concentrically through the side/side locking dovetail module **800** is a threaded bolt hole **828** that is configured to connect with the threaded top bolt **672** to lock an ice-skate sole **680** to the front and rear multi-degree of freedom arrangements **660** and **670**. In the present embodiment, the side/side dovetail module **800** is configured to move essentially perpendicular (in a non-arcued manner) to the contact axis **650**.

FIG. 9B illustratively depicts a front view line drawing of the side/side locking dovetail module **800** embodiment connected with the bi-directional locking dovetail module **700** embodiment consistent with embodiments of the present invention. The bi-directional locking dovetail module **700** includes a middle threaded ring **740** screwed onto the threaded cylinder **702**, which facilitates locking the side/side dovetail module **800** in a desired side adjustment. More specifically, the side/side dovetail **804** (which extends from the bottom portion **825** of the side/side dovetail module **800**) is engaged with the side/side dovetail channel **724** in a sliding/cooperating relationship. When the middle threaded ring **740** is twisted upwardly along the threads **701**, the middle threaded ring **740** contacts the side/side dovetail bottom **841**. As the middle threaded ring **740** is twisted to compress against the side/side dovetail bottom **841**, the side/side dovetail module **800** will be locked into a desired side/side position by way of contact compression between the side/side dovetail **804** and the pair of upper wedged shaped walls **710** that form the side/side dovetail channel **724**. In this manner, the side/side dovetail **804** and the side/side dovetail channel walls **710** are frictionally constrained together in place when mated under compression. Certain embodiments envision the middle threaded ring **740** tightened by a human hand, but optionally could be tightened with a tool, such as a wrench. In some embodiments, the middle threaded ring **740** possesses grips **722** to assist in tightening down or loosening up the middle threaded ring **740**. Accordingly, in this embodiment the side/side module **800** can be adjusted in a desired side/side position by sliding the side/side dovetail **804** inside of the side/side dovetail channel **724** when the middle threaded ring **740** it is not tightened down against the side/side dovetail bottom **841** fore/aft dovetail top **613**. Also shown here is a side/side centerline pointer **712**, which is located on at least one of the

outer surfaces 717 of the lower wedged shaped walls 710. The outer wall surface 717 is angled for improved viewing by an onlooker.

FIG. 9C illustratively depicts a top view line drawing of the side/side locking dovetail module 800 engaged with the bi-directional locking dovetail module 700 in a neutral position with respect to the connected mounting plate 405 consistent with embodiments of the present invention. FIG. 9D illustratively depicts a side view line drawing of the side/side locking dovetail module 800 with a defined view A-A depicted as an upward line of sight. The upward line of sight direction A-A allows an onlooker to see the plate bottom 825 without obstruction. FIG. 9E illustratively depicts the perspective the side/side locking dovetail module 800 from the A-A sight direction view. As shown, side/side graduated indicia 828 are visibly disposed on at least one side of the plate bottom surface 825 (if not on either side of the side/side dovetail 804 on the plate bottom surface 825). The side/side centerline pointer 712 is configured to point or otherwise line up with the side/side graduated indicia 828 to indicate the side-by-side position of the side/side locking dovetail module 800 relative to the bi-directional locking dovetail module 700.

FIGS. 9F-9H illustratively depict line drawings of the side/side locking dovetail module 800 adjusted to the far right position consistent with embodiments of the present invention. FIG. 9F is an isometric view of the side/side locking dovetail module 800 moved/adjusted to the far right. As discussed previously, the middle threaded ring 740 can be loosened so that it is not compressed against the side/side dovetail bottom 841 facilitating easy movement of the side/side dovetail channel 724 sliding over the side/side dovetail 804. Once in a desired forward position, the middle threaded ring 740 can be tightened to compress against the side/side dovetail bottom 841 thereby effectively locking the side/side dovetail 804 in the side/side channel 724. FIG. 9G illustratively shows a top view of the side/side locking dovetail module 800 moved to the far right. FIG. 9H illustratively depicts a perspective view of the side/side locking dovetail module 800 from the A-A line of sight. As shown, side/side graduated indicia 828 are visibly disposed on at least the plate bottom surface 825. The side/side centerline pointer 712 is configured to point, or otherwise line up, with the side/side graduated indicia 828 to indicate the far right side position. One skilled in the art will appreciate that the side/side locking dovetail module 800 can be adjusted in any number of positions within the bounds of the side/side graduated indicia 828 with respect to the bi-directional locking dovetail module 700.

FIG. 9I shows the side/side centerline pointer 712 pointing to the side/side graduated indicia 828 (not seen in this view) indicating that the side/side locking dovetail module 800 is moved to the far right. FIG. 9J shows the side/side centerline pointer 712 pointing to the side/side graduated indicia 828 (not seen in this view) indicating that the side/side locking dovetail module 800 is moved to the far left. When in FIGS. 9I and 9J are considered in light of FIGS. 6A-6E, it should be appreciated that the skate blade and runner 100/300 will effectively be shifted, or otherwise moved, in a desired side offset position relative to an ice-skating boot 699.

An optional embodiment envisions a modified side/side locking dovetail module 800 engaged with the bi-directional locking dovetail module 700 that is engaged with the pronate/supinate platform 600 or digital pronate/supinate platforms 651. The modified side/side locking dovetail module is envisioned not to connect with a Z height changing

elements but rather to attach directly into the ice-skating boot sole 680. This would effectively restrict the degree of freedom for the ice-skate (boot 699 and skate blade 100) to the supination directions a, and the fore and aft directions X₁ and X₂, and the side-by-side directions Y₁ and Y₂.

FIGS. 10A-10F illustratively depict line drawings of a lift ring embodiment cooperating with the side/side locking dovetail module 800 consistent with embodiments of the present invention. FIG. 10A is an isometric line drawing 10 illustratively depicting the lift ring 900 essentially encircling the threaded cylinder 802 of the side/side locking dovetail module 800. In the present embodiment, the lift ring top surface 902 has a concave arc 907 to accommodate an arced ice-skate sole 680 when adjusting in the fore/aft directions 15 (X₁ and X₂) along the sole 680. The lift ring top surface 902 interfaces with the attachment plates 665 and 675, which are inserted in the boot 699, the lift ring top surface 902 contacts or is otherwise constrained against the outside of the ice-skating boot sole 680 and therefore is above, or proper to, 20 the threaded cylinder top 816. To accommodate moving in different positions on the sole 680, the inside of the lift ring 900 comprises two lift ring alignment keys 906 that conform and engage the lift ring orientation recesses 818 in a limited rotating relationship to essentially keep the lift ring 900 oriented in the right direction. In other words, the lift ring concave arc 907 needs to remain in the orientation as shown with some built-in wiggle room to accommodate the ice-skating boot sole orientation recess 818 to keep the lift ring 900 oriented properly. Hence, if there is a single lift ring 25 orientation recess 818 then there only needs to be a single lift ring alignment key 906, and if the lift ring orientation recess 818 is a flat then the lift ring alignment key 906 only needs to be a matching flat.

In the present embodiment, the lift ring 900 is a universal 35 element with a constant lift ring thickness 912 that is between 0.2 inches and 0.4 inches thick. Certain embodiments envision the lift ring thickness 912 being approximately 0.25 inches thick. The lift ring 900 is adjustable in the Z direction (vertical Z₁ or Z₂ direction, see FIGS. 6B and 40 6C) by twisting the upper threaded ring 760 about the threaded cylinder 802, of the side/side locking dovetail module 800, in the Z direction. The lift ring bottom surface 904 interfaces or otherwise rests (by the downward force of 45 gravity) on the upper threaded ring 760 at interface 930. The lift ring can move in the Z direction to extend the height of the front and/or rear multi-degree of freedom arrangements 660 and 670 approximately as far as the height of the threads 801 of the threaded cylinder 802.

FIG. 10B illustratively depicts a side view of the lift ring 50 900 at a low position on the side/side locking dovetail module 800 consistent with embodiments of the present invention. The dashed lines near the lift ring top 902 represent where the threaded cylinder top 816 is positioned relative to the lift ring top 902. FIG. 10C illustratively 55 depicts the front view of the lift ring 900 at the low position on the side/side locking dovetail module 800 consistent with embodiments of the present invention. As shown here, the lift ring top 902 appears bowed, however that is the consistent shape of the front or rear side of the concave lift ring arc 60 907. FIG. 10D illustratively depicts a top view line drawing of the lift ring 900 showing space between the lift ring alignment keys 906 and the lift ring orientation recesses 818 to allow for some wiggle room.

FIGS. 10E and 10F illustratively depict front view line 65 drawings of the lift ring 900 in two different vertical positions consistent with embodiments of the present invention. As shown in FIG. 10E, the upper threaded ring 760 is

in the lowest position essentially against the upper surface of plate 826 with the threaded cylinder top 816 near, but under the lift ring top 902 as depicted by the dashed lines. As a consequence of spinning the upper threaded ring 760 to move upwards in the Z (vertical) direction, the lift ring 900 is raised in a higher position denoted by the location of the threaded cylinder top 816, as depicted in FIG. 10F. Because the lift ring 900 rests on the upper threaded ring 760 at interface 940, the upper threaded ring 760 pushes the lift ring 900 upwardly or lets the lift ring 900 lower. As the lift ring 900 is moved upwards or downwards (i.e., in the +/−Z directions) the ice-skate boot sole 680 is raised or lowered relative to the skate blade and runner 100/300, which in some circumstances can accommodate a skater's level of flexibility (such as ham string flexibility) over the skate, for example.

FIG. 10G illustratively depicts an isometric line drawing of the lift ring 900 in a raised vertical position consistent with embodiments of the present invention. The threaded cylinder top 816 is shown at a much lower point on the interior of the lift ring 900 as compared with FIG. 10A.

FIG. 10H illustratively shows a line drawing top view of the showing space between the lift ring alignment keys 906 and the lift ring orientation recesses 818 to allow for some wiggle room. In this embodiment, an angle of play ϕ between the lift ring alignment keys 906 and the lift ring orientation recess 818 can be between 0° and 10° , however embodiments are not limited by this range and other ranges are contemplated.

FIGS. 11A-11G illustratively depict line drawings of digital lift ring embodiments consistent with embodiments of the present invention. FIG. 11A is an isometric line drawing of an alternative embodiment showing a digital lift ring system 950 that connects directly with the bi-directional locking dovetail module 700. The lift ring system 950 can include a digital lift ring 960 that cooperates with a dovetail platform 958, the dovetail platform 950 incorporating a side/side dovetail 954. The side/side dovetail 954 cooperates with the side/side dovetail channel 724 associated with the bi-directional locking dovetail module 700. Certain embodiments envision the digital lift ring system 950 comprising a plurality of different sized, independent, rings 960-970 to provide varied Z heights for changing Z height (Z_1 and Z_2) of the bi-directional locking modules 700A and 700B. Front bi-directional locking module 700A is shown with the present configuration, as an example, though both of the bi-directional locking modules 700A and 700B can be configured with the side/side locking dovetail module 800 and lift ring 900 or the digital lift ring system 950. Though the present embodiment depicts the lift ring system 950 comprising a digital lift ring 960 and a separate dovetail platform 958 with a side/side dovetail 954, certain embodiments envision a lift ring system 950 being a unitary element. The lift ring system 950 whether a unitary element or not can be made out of metal, glass filled composite, any variety of polymers, carbon composite or other rigid/semi-rigid materials known to those skilled in the art applicable for this use.

FIGS. 11B and 11C are isometric line drawings that illustratively depict lift ring system 950 with two different sized lift rings consistent with embodiments of the present invention. FIG. 11B shows a low Z height digital lift ring 960 cooperating with a dovetail platform 956. FIG. 11C shows a high Z height digital lift ring 970 cooperating with a dovetail platform 956. As shown in both FIGS. 11B and 11C, there is a center threaded hole 925 adapted to receive threaded top bolt 672 to connect the bi-directional locking

modules 700A and 700B, reconfigured with the present embodiment, with an ice-skate boot sole 680.

FIGS. 11D and 11E are side view line drawings that illustratively depict the bi-directional locking dovetail module 700 cooperating directly with the lift ring system 950 consistent with embodiments of the present invention. FIG. 11D shows a side view of a low Z height digital lift ring 960 wherein the digital lift ring dovetail 954 is cooperating with the side/side channel 724, which is defined by the side/side channel walls 710. As previously discussed, the side/side dovetail channel 724 engages the lift ring dovetail 954 on the lift ring system 950 in a female to male relationship. As the middle threaded ring 740 is twisted upwards along the cylinder threads 701 against the dovetail platform 956, the pair of upper wedged shaped walls 710, that form the side/side dovetail channel 724, pull against the digital lift ring dovetail 954. This creates a contact compression which effectively locks the opposing dovetail components 724 and 954 together so that they are frictionally constrained in place, i.e., in the desired locked position. FIG. 11E shows a side view of the digital lift ring system 950 with a thick lift ring 972 provides a higher Z height than that of lift ring 960.

FIG. 11F illustratively depicts side views of multiple digital lift heights. Note that the profile of each digital lift ring has the concave arced lift profile 907. Certain embodiments envision each digital lift ring 0.05 inches in thickness, however the different thickness Z height is not limited by any particular value. For example, in one embodiment the lowest Z height lift ring "0" 960 is 0.05 inches wide, ring "1" 962 being 0.125 inches wide, ring "2" 964 being 0.20 inches wide, ring "3" 966 being 0.275 inches wide, ring "4" 968 being 0.35 inches wide, and ring "5" 970 being 0.425 inches wide. The term "wide" as used in conjunction with the lift rings 950 in this example is synonymous with the height in the Z direction. Of course, a skilled artisan after the benefit of understanding the present disclosure will appreciate that there could be far more sizes available for digital lift rings 950. FIG. 11G shows a top view of the different digital lift rings 950 depicted in FIG. 11F.

Certain embodiments contemplate any one or all of the adjusted elements can be used to establish a custom set of measurements. The custom set of measurements can then be used to create a one-piece mold, a multi-part mold, printed or machined part/s or some other physical model based on the specified measurements from the adjustable elements and processes discussed above. Some advantages of a custom measurement mold/s can include weight and the elimination of multiple parts, just to name several examples. Based on the indicia locations/measurements at each degree of freedom, it is envisioned that a custom post can be made to individualize the post for the physical attributes of the skater.

FIGS. 12A-12E illustratively depicts line drawings of a protective cup embodiment that protects the front and rear multi-degree of freedom arrangements 660 and 670 consistent with embodiments of the present invention. FIG. 12A is an isometric drawing of a protective cup embodiment 1000 that is adapted and configured to protect the front and rear multi-degree of freedom arrangements 660 and 670 from the insults of the external environment (e.g., hockey pucks, hockey sticks, rough handling/bumping into things, etc.). In the present embodiment, two protective cup sides 1002 and 1004 clamp together to surround a significant portion of the front and rear multi-degree of freedom arrangements 660 and 670. As shown, the protective cup arrangement 1000 is defined by a cup front 1008, a cup rear 1006, a cup bottom

surface 1014, and a cup top surface 1012. There is an upper accommodating multi-degree of freedom arrangement carve-out 1010 and a lower accommodating multi-degree of freedom arrangement carve-out 1011 that provide space for the front and rear multi-degree of freedom arrangements 660 and 670 to reside inside of the cup 1000. Certain embodiments envision the outer cup shell/surface 1025 made from a rigid and resilient material such as metal, polymer, nylon, glass filled composite, carbon composite, or other material that can provide the appropriate qualities of the protective cup arrangement 1000.

FIGS. 12B and 12C illustratively depicts side view line drawings of the right protective cup side 1004 consistent with embodiments of the present invention. As shown in FIG. 12B, the interior of the protective cup 1000 is mostly hollow 1022 but has locking grips 1020 arranged as ribs in the present embodiment. The locking grips 1020 surround and compress/conform to the front and rear multi-degree of freedom arrangements 660 and 670, and more specifically, the middle threaded ring 740 and the upper threaded ring 760, assuming the upper threaded ring 760 is used. In this way, the locking grips 1020 prevent the threaded rings 740 and 760 from spinning/turning and coming loose. Certain embodiments envision the locking grips 1020 being made of rubber, collapsible foam, collapsible metal, or other material that basically surrounds and locks the front and rear multi-degree of freedom arrangements 660 and 670 in place. In the present embodiment, there are two screw holes 1015 adapted and configured to receive threaded bolts or screws 1015. The threaded bolts or screws 1015 pull and clamp the two protective cup sides 1002 and 1004 together.

FIG. 12D illustratively depicts an isometric view line drawing of the right protective cup side 1004 with the entire internal locking grips 1020 consistent with embodiments of the present invention. As shown, the locking grips extend from the cup top surface 1012 to the cup bottom surface 1014, but provide a passageway for the front and rear multi-degree of freedom arrangements 660 and 670 shown via the upper carve-out 1010 and the lower carve-out 1011. Also shown for reference is the threaded bolt or screw 1015 that screws the two sides 1002 and 1004 together.

FIG. 12E illustratively depicts the cup arrangement 1000 engaged with the rear multi-degree of freedom arrangement 670 consistent with embodiments of the present invention. In the present embodiment, the cup arrangement 1000 is clamped around a portion of the rear multi-degree of freedom arrangement 670 without obstructing the rear attachment plate 675 or the lower threaded ring 720. It is self-evident that the rear attachment plate 675 needs clear axis for attaching to the ice-skate sole 680 and is therefore uncovered. The lower threaded ring 720 is uncovered so that a person can loosen (by twisting) the lower threaded ring 722 facilitate quick release of the skate blade and runner assembly 100/103 by disengaging the fore/aft dovetail 606 with the fore/aft channel 724 as described earlier. A second cup arrangement is envisioned to cover the front multi-degree of freedom arrangement 660 similar to that shown for the rear multi-degree of freedom arrangement 670.

FIGS. 13A-13J are various line drawing views of an optional skate riser system embodiment consistent with embodiments of the present invention. FIG. 13A is a line drawing of a front facing isometric view of a neutral skate riser system embodiment 1100 looking down on the top surface of the adapter mount 1130. As shown, the skate riser system 100 generally includes a riser 1105 (also referred herein to as a “post”) interposed between a boot adapter mount 1130 and a skate runner mount 1120. The boot

adapter mount 1130 is configured to connect the skate riser system 1100 to a skate boot sole 680 of an ice-skate boot 699, as shown in FIG. 6F. Optional embodiments contemplate the adapter mount 1130 connecting to a boot sole of a non-ice skate boot, such as a rollerblade boot for example. In this embodiment, the boot adapter mount 1130 comprises a center adapter mount bolt hole 1132 that is between two side bolt holes 1134. The center adapter mount bolt hole 1132 is configured to attach the boot adapter mount 1130 to the riser 1105 and the side boot holes 1134 are arranged and configured to attach the boot adapter mount 1130 to a boot sole 680. In this embodiment, the center adapter mount bolt hole 1132 is countersunk to receive a flat head bolt. As explained below in more detail, the skate runner mount 1120 is removably connected to the riser 1105 via a quick release shaft 1110 that cooperates with retaining block 1125, which is part of the skate runner mount 1120. The quick release shaft 1110 extends into at least part of the riser 1105 via a shaft sleeve 1106.

FIG. 13B is a line drawing of a front facing isometric view of the neutral skate riser system embodiment 1100 looking up at the bottom of the skate runner mount 1120 (i.e., at the skate runner interface 1122). As should be appreciated, the riser 1105 is connected to the skate runner mount 1120 via the quick release shaft 1110. With regards to the skate runner mount 1120, the skate runner interface 1122 is configured to cooperate or otherwise slidingly engage the skate overmold mounting plate 405 (or a similar overmold mounting surface), as shown in FIG. 5C. On either end of the skate runner interface 1122 is a supinate/pronate detent 1124 that mates with pin at the top of the skate overmold mounting plate 405. The pin/detent configuration can just as easily be swapped with the detent being on the mounting plate 405, for example. Moreover, other retention features known to those skilled in the art can be implemented to resist movement between the mounting plate 405 and the skate runner interface 1122 once clamped together. Certain other embodiments envision no detent mating with a pin to facilitate various pronate/supinate adjustment of the skate runner interface 1122 over the skate overmold mounting plate 405. Note the side boot hole 1134 in the boot adapter mount 1130 is countersunk to receive a flat head bolt, which is used to screw into a receiving hole in the boot sole 680 to attach the boot adapter mount 1130 to a boot sole 680.

FIG. 13C is a line drawing of a front view of the neutral skate riser system 1100 depicting a common longitudinal plane 1135 running along (extending through) the center of the skate riser system 1100 bisecting the adapter mount 1130, riser 1105 and the skate runner mount 1120. The common longitudinal plane 1135 is defined along the frontal center point 1123 at the riser front 1103A (and the rear 1103B) of the skate runner mount 1120. As shown, the skate riser system 1100 is a neutral skate riser because the right riser side 1101A is symmetric with the left riser side 1101B as defined about the common longitudinal plane 1135. In this embodiment, the riser sleeve 1106 extends on either side of the riser sides 1101A and 1101B. The skate runner mount 1120 is connected to the riser 1105 via the quick release shaft 1110, as shown. Also shown, is the arc shaped skate runner interface 1122 that provides for adjustment in pronation and supination.

FIG. 13D is a line drawing of a side view of the neutral skate riser system 1100 depicting a common frontal plane 1136 running along or otherwise extending through the center of the skate riser system 1100 bisecting the adapter mount 1130, riser 1105 and the skate runner mount 1120 with the riser front 1103A and the riser back 1103B sym-

metrically laid out on either side of the frontal plane 1136. The common frontal plane 1136 is centered along the longitudinal center point 1173 of the skate runner mount 1120. The riser 1105 is also centered over the skate runner mount 1120 shown by the skate runner mount 1120 that is bisected by the common frontal plane 1136. The common frontal plane 1136 is defined by the frontal center point 1121 on either side 1101A and 1101B of the skate runner mount 1120.

FIG. 13E is a line drawing of a top side view of the neutral skate riser system 1100 showing the relationship of the boot adapter mount 1130 relative to the riser 1105 and the skate runner mount 1120.

FIG. 13F is a line drawing of a bottom side view of the neutral skate riser system 1100, showing the relationship of the boot adapter mount 1130 relative to the riser 1105 and the skate runner mount 1120 but with the skate runner surface 1122 facing the viewer. Also, for reference are the common frontal plane 1136 and the common longitudinal plane 1135.

FIG. 13G is a line drawing of an exploded isometric view of the skate riser system embodiment 1100 looking down on the top surface of the boot adapter mount 1130. As shown in this embodiment, the boot adapter mount 1130 fits in a channel defined between adapter mount lips 1109 at the boot adapter mount end 1102 of the riser 1105. The channel at the adapter mount end 1102 closely conforms to the boot adapter mount 1130, which holds the boot adapter mount 1130 in the appropriate position relative to the riser 1105. Note the center adapter mount bolt hole 1132 aligns with a receiving hole 1131 in the boot adapter mount end 1102 of the riser 1105, which are held together by a center bolt (not shown). The quick release shaft 1110 is illustratively depicted outside and to the left of the riser 1105. A straight arrow indicates where the quick release shaft 1110 is inserted in the riser sleeve aperture 1108. The riser sleeve aperture extends into the riser sleeve 1106. The quick release shaft 1110 comprises a keyed portion, or simply a key 1112 that is thinner (smaller dimension) than the diameter of the shaft outer diameter 1114. In this embodiment, the shaft head 1118 comprises a hex socket 1119, however other gripping and turning arrangements are envisioned within the knowledge of those skilled in the art without departing from the scope and spirit of the present invention. This quick release shaft arrangement 1110 further comprises a pair of rubber O-rings 1111 disposed on either side of the key 1112, which add some resistance when the quick release shaft 1110 is rotated in a locked or unlocked orientation via an Allen wrench engaged in the hex socket 1119. Certain embodiments contemplate the quick release shaft 1110 being captured or otherwise prevented from freely pulling out of the riser sleeve aperture 1108. Below the riser 1105 is the skate runner mount 1120, which is intended to slide inside of the riser 1105 at the skate runner mount end 1104. The skate runner mount 1120 comprises a retaining block 1125 that has a shaft retention channel 1126 that extends through the retaining block 1125, as shown. The retaining block 1125 extends towards the riser 1105 of the retaining block base 1127.

FIG. 13H is a line drawing of an exploded isometric view of the skate riser system embodiment 1100 looking up from the bottom surface of the skate runner mount 1120. From this perspective, all the bottom sides of the main components are shown, such as the boot adapter mount 1130 and the riser 1105. As depicted, the riser 1105 comprises a cavity 1107 that is configured to receive the retaining block 1125. In this embodiment, the cavity 1107 is shaped like the retaining

block 1125 (i.e., the inverse shape of the retaining block 1125) with the appropriate tolerances to allow for easy insertion of the retaining block 1125. Hence, the inner border 1103 at the skate runner mount end 104 is essentially the same shape and size as the retaining block base 1127 to provide a snug fit when the retaining block 125 is inserted in the cavity 1107. As shown from this perspective, the riser sleeve aperture 1108 extends through the riser 1105 and into the riser sleeve 1106 on the left side of the riser 1105. The shaft head 1118 positions the quick release shaft 1110 with the key portion 1112 in the right location in the cavity 1107.

FIG. 13I is a line drawing of an exploded side view of the skate riser system embodiment 1100 with the quick release shaft 1110 coming out of the page. From this perspective, the boot adapter mount channel, which is defined by the boot adapter mount lips 109, clearly shows the position retaining relationship between the riser 1105 and the boot adapter mount 1130. With more detail to the retaining block 1125, the circular shaft retention channel 1126 is configured to receive and engage the cylindrical quick release shaft 1110. In this embodiment, the shaft retention channel 1126 is semicircular in shape due to a gap 1129 in the top part of the retention block 1125. The semicircle is between 210° and 320°, wherein the gap 1129 is narrower than the shaft outer diameter 1114 to capture the quick release shaft 1110 when the flat portion of the key 1112 is facing downward (i.e., when the key is in a locked orientation). Accordingly, when the skate runner mount 1120 is in contact with the skate runner mount end 1104 and the key 1112 is rotated in a locked orientation, the channel overhang 1128 retains the quick release shaft 1110 in the shaft retention channel 1126 thereby retaining the skate runner mount 1120 to the riser 1105 (or in other words the skate blade 100 to the skate boot 699).

FIGS. 13J and 13K are line drawings illustrating the quick release mechanism embodiment when the quick release shaft 1110 (which can be captured in the riser 1105) is rotated between a locked and unlocked orientation. The quick release shaft 1110 is considered captured in the riser 1105 when it is unable to freely be pulled out from the riser sleeve aperture 1108. The quick release mechanism provides an athlete with the ability to swap out one skate blade for another very quickly, such as to replace a dull blade for a sharp blade or to swap out blades with different fore/aft offsets.

FIG. 13J depicts the quick release arrangement in a locked orientation, wherein the quick release shaft 1110 is rotated in the shaft retention channel 1126 with the flat part of the key portion 1112 facing downward (see arrow 1138) and the shaft outer diameter 1114 trapped in the channel overhangs 1128. Because the shaft outer diameter 1114 is larger than the channel gap 1129, when the quick release shaft 1110, is rotated in this way, the skate runner mount 1120 is locked in the riser 1105 thereby locking the skate blade 100 to the skate boot 699.

FIG. 13K depicts the quick release arrangement in an unlocked orientation, wherein the quick release shaft 1110 is rotated in the shaft retention channel 1126 with the flat part of the key portion 1112 facing sideways so that the quick release shaft 1110 can freely slide out from the channel gap 1129. Hence, when the quick release shaft 1110 is rotated in the open arrangement, the skate runner mount 1120 can disengage or otherwise slide out from the riser cavity 1107 thereby disengaging the riser 1105 from the skate runner and overmold 300. In this way, the skate runner mount 1120 is unlocked from the riser 1105, which permits the skate blade 100 to disengage from the skate boot 699.

FIGS. 14A-14C are line drawings of various views of a side offset skate riser system consistent with embodiments of the present invention. The side offset skate riser system 1150 provides enhanced flexibility for a skater who wants to custom locate the skate blade 100 in a side offset position relative to the longitudinal mid-line 1192 of the skate boot 699 to better situate the skate under the boot 699 to adjust for the skater's unique style of skating. The longitudinal midline is along the midplane 1190 of the boot 699, which extends vertically along a neutral axis 1192 of the boot sole 680 as shown in FIG. 17B. FIG. 14A is a front view of a side offset riser system 1150, wherein the side-offset riser 1155 is shifted an offset amount 1156 to the left, thereby shifting the boot adapter mount 1130 to the left as well. More specifically, the frontal center 1157 of the boot adapter mount 1130 (shown in FIG. 14C) is defined along a longitudinal offset plane 1158, which is parallel and offset to the common longitudinal plane 1135. As shown here, the left riser side 1151B is not symmetric with the right riser side 1151A. Certain embodiments envision a plurality of different side offset skate riser systems 1150 each with a different side offset. For example, a first side offset skate riser system can be offset 2 mm to the left (i.e., have an offset amount 1156 of 2 mm), which means that the longitudinal offset plane 1158 is offset to the left 2 mm from the common longitudinal plane 1135, and a second side offset skate riser system can be offset 4 mm to the left, and yet a third side offset skate riser system can be offset 6 mm to the left, etc. A skilled artisan will appreciate that there can be an infinite number of different side offset skate risers 1155 without departing from the scope and spirit of the present invention. Some embodiments envision a side offset riser 1155 equally being provided with an offset to the right, while other embodiments envision a left-sided offset skate riser system being obtained by the side offset skate riser system 1150 simply being rotated 180° to create a right-sided offset a riser system.

FIG. 14B depicts a side view of the side offset riser system 1150 of FIG. 14A. As shown here, the boot adapter mount 1130, the side-offset riser 1155 and the skate runner mount 1120 are all centered along the common frontal plane 1136. Hence, there is no fore or aft shift in the adapter mount 1130. Also, the riser front 1153A and the riser back 1153B of the side-offset riser 1155 are symmetric about the common frontal plane 1136.

FIG. 14C is a top view of the side offset riser system 1150 of FIG. 14A depicting the boot adapter mount 1130 shifted to the left of the common longitudinal plane 1135 with the offset amount 1156 as shown in FIG. 14A. That is, the frontal center 1157 of the boot adapter mount 1130, which is along the longitudinal offset plane 1158, is shifted to the left of the common longitudinal plane 1135. Note, the boot adapter mount 1130, the side-offset riser 1155 and the skate runner mount 1120 are all centered along the common frontal plane 1136.

FIGS. 15A-15D are line drawings illustratively depicting various views of a side offset and fore/aft offset skate riser system consistent with embodiments of the present invention. FIG. 15A is a front view of a side and fore/aft offset riser system 1170, wherein the side-offset riser 1155 is the same as that presented in conjunction with FIG. 14A. As mentioned earlier, the boot mount end 1102 of the side-offset riser 1155 can be shifted (or offset) to the left or right of the common longitudinal plane 1135 thereby shifting the boot adapter frontal center 1157 of the boot adapter mount 1130 to the left or right of the common longitudinal plane 1135.

FIG. 15B depicts the side view of the side and fore/aft offset riser system 1170 of FIG. 15A. The fore/aft offset riser

system 1170 provides enhanced flexibility for a skater to custom locate the skate blade 100 in a fore or aft position relative to the heel 696 and toe 698 of the skate boot 699 to enhance the skater's unique style of skating. As shown here, the boot adapter mount 1130 and the side-offset riser 1155 are centered along the frontal offset plane 1172, which is shifted to the right of the common frontal plane 1136 a fore/aft amount 1176, such as 2 mm, 4 mm, or 6 mm, just to name three examples of an infinite number of fore/aft offset values. The common frontal plane 1136 is centered along the longitudinal center point 1173 of the skate runner mount 1175. Hence, there is a fore or aft shift of the skate blade 100 relative to the heel 696 and toe 698 of the skate boot 699. Certain embodiments envision a plurality of different fore/aft skate runner mounts 1175 with the retaining blocks 1125 being offset from the longitudinal center point 1173 of the runner mount 1175.

FIG. 15C shows a top view of the fore/aft offset riser system 1170 of FIG. 15A depicting the boot adapter mount 1130 (defined along the longitudinal offset plane 1158) shifted to the left of the common longitudinal plane 1135 in addition to being shifted away from the common frontal plane 1136 as shown by the spacing from the frontal offset plane 1172. That is, along with the boot adapter mount 1130 being shifted to the left of the common longitudinal plane 1135, the boot adapter mount 1130 is shifted towards the rear 1178 of the fore/aft skate runner mount 1175. That is, frontal offset plane 1172, that runs down the middle of the boot adapter mount 1130, is shifted away from the common frontal plane 1136. In certain embodiments, the fore/aft offset riser system 1170 can simply be rotated 180 degrees to function as a fore offset riser system or and aft offset riser system. It should be appreciated that the present embodiment can comprise a neutral riser, like the riser 1110 of FIG. 13A.

FIG. 15D is an exploded view of the fore/aft offset riser system 1170 of FIG. 15A to depict the placement of the retaining block 1125 relative to the fore/aft skate runner mount 1175. As shown here, the retaining block 1125 is centered along the frontal offset plane 1172 with the side offset riser 1155 and the boot adapter mount 1130. However, the center of the retaining block 1125 (centered along the frontal offset plane 1172) is shifted to the right of the common frontal plane 1136. In this embodiment, the retaining block 1125 and the fore/aft skate runner mount 1175 make up a unitary element (i.e., is a single piece of material, which could be machined, printed, or molded, for example), however other embodiments contemplate otherwise.

FIGS. 16A and 16B are line drawings of an optional embodiments of a riser system with varied riser heights (Z-heights) consistent with embodiments of the present invention. The varied Z-height riser system embodiment 1180 provides enhanced flexibility for a skater to customize the distance between their boot sole 680 the skate blade 100 to accommodate their unique style of skating. FIG. 16A illustratively depicts a varied Z-height riser system 1180 that is the same as that shown in FIGS. 15A-15D but with a riser 1185 that has a larger Z-height 1184 than the riser 1155. Hence, except for increasing the distance between the skate blade 100 and the boot sole 680, the Z-height riser system embodiment 1180 comprises a boot mount end 1102 of the side-offset and Z-height adjusted riser 1185 shifted (or offset) to the left of the common longitudinal plane 1135 thereby shifting the boot adapter frontal center 1157 of the boot adapter mount 1130 to the left of the common longitudinal plane 1135. It should be appreciated that the present

embodiment can comprise a neutral riser like the riser 1110 of FIG. 13A but with a larger or smaller Z-height 1184.

FIG. 16B depicts a side view of the varied Z-height riser system 1180 comprising the same as that shown in FIGS. 15A-15D but with a riser 1185 that has a larger Z-height 1184 than the riser 1155 and with the boot adapter mount 1130 shifted towards the rear 1178 of the fore/aft skate runner mount 1175.

With the embodiments of FIGS. 13A-16B in mind, it should be appreciated that different risers having different Z-heights 1184, whether neutral or offset to the left or right, can be employed without departing from the scope and spirit of the present invention. Furthermore, any of the riser embodiments can be matched with any number of different skate runner mounts, whether a skate runner mount is a neutral skate runner mount 1120 or a fore/aft skate runner mount 1175.

FIGS. 17A-17D depict optional skate runner mounts used with a blade and boot illustrating the combination of various offsets mounted to a skate. Certain embodiments envision a fully adjustable skate riser system 660 (i.e., the front and rear multi-degree of freedom arrangements 660 and 670 of FIG. 6A, for example) being used to find a particular Z-offset, side-offset, fore or aft offset that appeals to a skater. Once found, a skate riser system, such as 1100, 1150, 1175, etc., can be made or provided that matches or closely matches those offsets found from the fully adjustable skate riser system 660, just to name one method of figuring out the disclosed offsets. As can be appreciated in this ure, certain embodiments of the present invention contemplate an optional arrangement with each of the offset attributes encompassed in a single piece of material that includes the riser 1105, the skate runner mount 1120 and the boot adapter mount 1130 with or without the quick release shaft system 1110 (uni-riser). In other words, a single offset skate riser system (such as 1100) can be manufactured as a unitary element or optionally with certain parts described above integrated as one (e.g., a riser 1105 integrated with the boot adapter mount 1130).

FIGS. 17A and 17B are line drawings of a neutral skate riser system 1100 connecting a skate runner to a skate boot consistent with embodiments of the present invention. FIG. 17A is a side view of the neutral quick release skate riser system 1100 connecting a skate blade 100 with a skate boot 699. FIG. 17B depicts the front view of the neutral quick release skate riser system 1100 connecting a skate blade 100 with a skate boot 699.

FIGS. 17C and 17D are line drawings of a side-offset and aft-offset skate riser system 1170 used to connect a skate runner to a skate boot consistent with embodiments of the present invention. FIG. 17C is a side view of the side-offset and aft-offset skate riser system 1170 with the quick release shaft 1110 withdrawn from the riser 1155 and the skate blade 100 disconnected from the skate boot 699. In certain embodiments, the quick release shaft 1110 need only be rotated, as shown in FIGS. 13J and 13K, to release the skate blade 100 from the skate boot 699. FIG. 17D depicts the front view of the side-offset and aft-offset skate riser system 1170 with the quick release shaft 1110 withdrawn from the riser 1155 and the skate blade 100 disconnected from the skate boot 699.

With the present description in mind, below are some examples of certain embodiments illustratively complementing some of the methods and apparatus embodiments discussed above and presented in the figures to aid the reader. Accordingly, the elements called out below are provided by example to aid in the understanding of the

present invention and should not be considered limiting. The reader will appreciate that the below elements and configurations can be interchangeable within the scope and spirit of the present invention. The illustrative embodiments can include elements from the figures.

In that light, certain embodiments contemplate a skate riser system 1100, as shown in FIGS. 13A-17D, comprising a riser 1105 defined between a boot adapter mount end 1102 and a skate runner mount end 1104, wherein the riser 1105 is not adjustable. The skate riser system 1100 further comprises a boot adapter mount 1130 that is connected to the boot adapter mount end 1102. The boot adapter mount 1130 is configured to connect to a boot sole 680 of a skate boot 699. A quick release shaft 1110 extends into a riser aperture 1108 in the riser 1105 between the ends 1102 and 1104. The quick release shaft 1110 comprises a key 1112 that retains a skate runner mount 1120 to the riser 1105 when in a first position/orientation 1115 but not when in a second position/orientation 1116.

Another embodiment of the skate riser system 1100 envisions the riser 1105 comprising a sleeve 1106 that extends from at least one riser side 1107 of the riser 1105, wherein the sleeve 1106 accommodates the quick release shaft 1110 axially along the sleeve 1106. In certain embodiments the sleeve 1106 is cylindrical.

The embodiment of the skate riser system 1100 further imagines the skate runner mount 1120 comprising a retaining block 1125 that extends into the riser 1105 at the skate runner mount end 1104, wherein a shaft retention channel 1126 in the retaining block 1125 cooperates with the quick release shaft 1110. Some embodiments envision the key 1112 being a narrowing slot in a portion of the quick release shaft 1110 that when rotated in the first position/orientation 1115 is not captured by the shaft retention channel 1126 but when rotated in the second position 1116 is captured by the shaft retention channel 1126. Further embodiments envision that when the quick release shaft 1110 is rotated in the first position 1115, the riser 1105 is not fixedly attached to the skate runner mount 1120 but when the quick release shaft 1110 is rotated in the second position 1116, the riser 1105 is fixedly attached to the skate runner mount 1120. Optional embodiments contemplate the quick release shaft 1110 being cylindrical and the shaft retention channel 1126 conforming to the quick release shaft 1110, wherein the shaft retention channel 1126 comprises a semicircular cross section that is between 210 degrees and 320 degrees.

The embodiment of the skate riser system 1100 further contemplates the riser being a side offset riser 1155 that shifts a skate blade to the left or right of a sole midplane 1190 that extends vertically along a neutral axis 1192 of the boot sole 680.

The embodiment of the skate riser system 1100 further imagines the skate runner mount being a fore/aft offset skate runner mount 1175 that shifts a skate blade towards a heel end 696 or toe end 698 of the skate boot 699.

The embodiment of the skate riser system 1100 further envisions the riser 1105 having a different Z-height 1184 than a second riser (a different riser).

The embodiment of the skate riser system 1100 further contemplates the skate runner mount 1120 comprising an arc shaped skate runner interface 1122 that is configured to rotate the boot sole 680 out from a sole midplane 1190, the sole midplane 1190 extends vertically along a neutral axis 1192 of the boot sole 680 for adjustment in pronation and supination directions.

Yet another embodiment of the present invention envisions a skate riser and quick release apparatus 1100 com-

prising a static riser 1105 having a boot adapter mount 1130 configured to attach to a boot sole 680, and a skate runner mount 1120 that extends from a skate runner 300. The skate runner mount 1120 can be removably connected to the static riser 1105 via a quick release shaft 1110 that extends through the skate runner mount 1120 and at least a portion of the static riser 1105.

The embodiment of the skate riser and quick release apparatus 1100 further envisions the skate runner 300 being connected to either an ice-skate blade 100 or a plurality of roller-blade wheels.

The embodiment of the skate riser and quick release apparatus 1100 further imagining the skate runner mount 1120 being adjustably attached to the skate runner 300 in a neutral, pronate or supinate relationship.

The embodiment of the skate riser and quick release apparatus 1100 further envisioning the static riser 1105 comprising a different side offset and/or a different Z-height than a second static riser 1155/1185, wherein the side offset riser shifts a skate blade to the left or right of a sole midplane 1190 extends vertically along a neutral axis 1192 of the boot sole 680.

The embodiment of the skate riser and quick release apparatus 1100 further envisions the quick release shaft 1110 comprising a key 1112 that when rotated in an unlocked position from a locked position, the skate runner mount 1120 becomes disengaged from the static riser 1105.

Another embodiment of the present invention contemplates a method for disengaging a skate runner from a skate boot. The method is to a riser 1105 that comprises a boot adapter mount 1130 configured to attach to a boot sole 680 at one end and a skate runner mount 1120 at the other end. The skate runner mount 1120 extends from a skate runner 300. One step is for engaging a retaining extension 1125 that extends from the skate runner mount 1120 in an overlapping relationship with the riser 1105, wherein when in the overlapping relationship a runner mount retaining channel 1126 of the retaining extension 1125 aligns with a riser channel 1108 of the riser 1105. Another step is a step for locking the retaining extension 1125 to the riser 1105 via a quick release shaft 1110 that extends through the riser channel 1108 and the runner mount retaining channel 1126.

The method embodiment further envisions unlocking the retaining extension 1125 from the riser 1105 by rotating the quick release shaft 1110 in an unlocked orientation while the quick release shaft 1110 remains extended through the riser channel 1108 and the runner mount retaining channel 1126.

The method embodiment further imagines the retaining extension 1125 is a retaining block that extends into a riser cavity 1107 of the riser 1105 and the riser channel 1108 captures the quick release shaft 1110 from disengaging from the riser 1105.

The method embodiment further imagines that the locking step is accomplished via a key 1112 in the quick release shaft 1110 when the quick release shaft 1110 is rotated in a locking orientation and wherein an unlocking step is accomplished by disengaging the skate runner 300 from the boot sole 680 by unlocking the retaining extension 1125 from the riser 1105 by rotating the quick release shaft 1110 in an unlocking orientation.

Still some other embodiments presented herein include:

Embodiment 1: A skate runner 100 comprising: an elongated skate runner body 103 that extends between a front end 190 and a rear end 192 defining a blade length 195; a bottom region 104 defining a bottom width 128 and a top region 118 defining a top width 126; a blade edge 101 located at the bottom region 104, the blade edge 101 is

configured to contact an ice sheet 177, the blade edge 101 extending in a vertical direction 123 terminating at a blade top 121; a neutral plane defined along a central axis 314 centrally located in the bottom width 128 in the vertical direction and along the blade length 195; the top width 126 narrower than the bottom width 128; and a stress relieving radius 110 that joins the top region 118 to the bottom region 104, the skate runner 100 is a unitary structure.

Embodiment 2: The skate runner of embodiment 1 wherein the top region 118 is essentially encased in a polymeric overmold core 200 that extends in the vertical direction 123 beyond the blade top 121 terminating at an overmold core top 204.

Embodiment 3: The skate runner of embodiment 2 wherein the polymeric overmold core 200 is essentially encased in a skate overmold 300 that is essentially defined by an overmold top surface 310 and overmold side walls 308 which terminates at a blade/overmold interface 312, the overmold top surface 310 possessing a front mounting surface 302 and a rear mounting surface 304.

Embodiment 4: The skate runner of embodiment 3 wherein the skate overmold 300 is a different material than the skate over mold core 200.

Embodiment 5: The skate runner of embodiment 3 wherein the front mounting surface 302 and a rear mounting surface 304 further possess female interlocking mount receptacles 306.

Embodiment 6: The skate runner of embodiment 5 wherein the female interlocking mount receptacles 306 cooperate with male interlocking mounts 400A or 400B.

Embodiment 7: The skate runner of embodiment 5 wherein the female interlocking mount receptacles 306 cooperate with male interlocking mounts 400B that extend from a bottom side 418 of a mounting plate 405, the mounting plate 405 comprising an arced mounting surface on a top side 414.

Embodiment 8: The skate runner of embodiment 7 wherein each of the mounting plates 405 and the male interlocking mounts 400B are unitary.

Embodiment 9: The skate runner of embodiment 8 wherein each of the arced mounting plates 405 possesses pronate/supinate graduated indicia 416 visibly disposed on at least a front surface 410.

Embodiment 10: The skate runner of embodiment 7 wherein each of the mounting plates 405 possess tapped holes 412 adapted to receive threaded male fasteners.

Embodiment 11: The skate runner of embodiment 3 wherein the front mounting surface 302 and a rear mounting surface 304 are each removably connected with a mounting plate 405.

Embodiment 12: The skate runner of embodiment 11 wherein each of the mounting plates 400 possess a convex arc cylinder segment 405 that arcs around a contact axis 650 defined by a rocker high point 113 of the blade edge 101 and the neutral plane 315.

Embodiment 13: The skate runner of embodiment 12 further comprising a pronate/supinate platform 600 that possesses a concave arc 609 that mates with the convex arc cylinder segment 405.

Embodiment 14: The skate runner of embodiment 13 further comprising pronate/supinate graduations 416 visibly located on at least a front surface 410 of the mounting plates 400 that cooperate with a pronate/supinate centerline pointer 611 on the pronate/supinate platform 600.

Embodiment 15: The skate runner of embodiment 13 wherein the pronate/supinate platform 600 is adjustably attached to the convex arc cylinder segment 405.

Embodiment 16: The skate runner of embodiment 15 wherein the pronate/supinate platform **600** is adjustably rotated about the contact axis **650** in a pronation position **635** or a supination position **645**.

Embodiment 17: The skate runner of embodiment 16 further comprising fore/aft graduated indicia **616** visibly disposed on at least one pronate/supinate platform side surface **619** below a fore/aft dovetail **606** extending along a top portion of the pronate/supinate platform **600**.

Embodiment 18: The skate runner of embodiment 13 further comprising a fore/aft dovetail **606** extending longitudinally parallel to the contact axis **650** along a pronate/supinate platform top surface **613** obverse to the concave arc **609**.

Embodiment 19: The skate runner of embodiment 18 further comprising a bi-directional locking dovetail module **700** that includes: a threaded cylinder **A 702**; a fore/aft dovetail channel **706** extending from bottom side **A 714** of the threaded cylinder **A 702** that slidably engages the fore/aft dovetail **606** parallel to the contact axis **650**; and a side/side dovetail channel **724** extending from a threaded cylinder **A** top side **716** that extends essentially perpendicular to the contact axis **650**.

Embodiment 20: The skate runner of embodiment 19 further comprising a threaded ring **A 720** that is rotatably engaged with threads **A 701** on the threaded cylinder **A 702**.

Embodiment 21: The skate runner of embodiment 20 wherein the threaded ring **A 720** is in a locking position when the threaded ring **A 720** is in contact compression with the pronate/supinate platform top surface **613**, the fore/aft dovetail **606** is in compression with the fore/aft dovetail channel **706**; the threaded ring **A 720** is in an unlocking position when the threaded ring **A 720** is not in the contact compression with the fore/aft dovetail **606**.

Embodiment 22: The skate runner of embodiment 20 wherein the threaded ring **A 720** possess grips **722**.

Embodiment 23: The skate runner of embodiment 13 wherein the fore/aft dovetail can be disconnected from the fore/aft dovetail channel **706** by loosening the threaded ring **A 720**.

Embodiment 24: The skate runner of embodiment 21 further comprising a centerline pointer **B 711** visibly located on the fore/aft dovetail channel **706**, the centerline pointer **B 711** cooperates with the fore/aft graduated indicia **616**.

Embodiment 25: The skate runner of embodiment 21 further comprising a centerline pointer **C 712** visibly located on the side/side dovetail channel **724**.

Embodiment 26: The skate runner of embodiment 19 further comprising a side/side dovetail module **800** that includes a side/side dovetail **804** extending from a bottom side **B 814** of a threaded cylinder **B 802**, threaded cylinder **B 802** possesses threads **B 801** on the threaded cylinder **B 802**, the side/side dovetail **B 804** slidably engages the side/side dovetail channel **724** that is essentially perpendicular to the contact axis **650**.

Embodiment 27: The skate runner of embodiment 24 further comprising a threaded ring **B 740** that is rotatably engaged with threads **A 701** on the threaded cylinder **A 702**.

Embodiment 28: The skate runner of embodiment 27 wherein the threaded ring **B 740** is in a locking position when the threaded ring **B 740** is in contact compression with the side/side dovetail **804** the side/side dovetail **804** is in compression with the side/side dovetail channel **724**; the threaded ring **B 740** is in an unlocking position when the threaded ring **B 740** is not in the contact compression with the side/side dovetail **804**.

Embodiment 29: The skate runner of embodiment 28 wherein the threaded cylinder **B 802** possesses at least one lift ring orientation recess **818** that extends into the cylinder surface **B 803** between the bottom side **B 814** to a cylinder **B** top surface **816** of the threaded cylinder **B 802**.

Embodiment 30: The skate runner of embodiment 29 wherein the at least one lift ring orientation recess **818** is either a channel or a flat.

Embodiment 31: The skate runner of embodiment 30 further comprising a plate **826** interposed between the side/side dovetail **804** and the bottom cylinder side **B 814**, the plate **826** defining a plate surface **825** from which the side/side dovetail **804** extends, side/side graduated indicia **828** visibly located on the plate surface **825**, the side/side graduated indicia **828** cooperating with the centerline pointer **C 712**.

Embodiment 32: The skate runner of embodiment 29 further comprising a lift ring **900** that encircles the threaded cylinder **B 802**, the lift ring **900** possessing at least one lift ring alignment key **906** that engages the at least one lift ring orientation recess **818** in a limited rotating relationship.

Embodiment 33: The skate runner of embodiment 32 wherein the limited rotating relationship provides up to 20 degrees of rotation between the lift ring **900** and the threaded cylinder **B 802**.

Embodiment 34: The skate runner of embodiment 32 wherein the lift ring **900** terminates at a lift ring top surface **902** that when engaged with the threaded cylinder **B 802** is above the cylinder **B** top surface **816**.

Embodiment 35: The skate runner of embodiment 32 wherein the lift ring **900** terminates at a lift ring top surface **902** that when engaged with the threaded cylinder **B 802** is above the cylinder **B** top surface **816**.

Embodiment 36: The skate runner of embodiment 34 wherein lift ring top surface **902** is concave with a low point **907** essentially in line with the side/side dovetail **804**.

Embodiment 37: The skate runner of embodiment 32 further comprising a threaded ring **C 760** rotationally engaged with the threaded cylinder **B 802**, the lift ring **900** rests on the threaded ring **C 760**.

Embodiment 38: The skate runner of embodiment 37 wherein the lift ring **900** is in a low position **930** on the threaded cylinder **B 802** when the ring **C 760** is disposed essentially at the bottom side **B 814** of the threaded cylinder **B 802** and the lift ring **900** is in a high position **940** on the threaded cylinder **B 802** when the ring **C 760** is disposed essentially at the cylinder **B** top surface **816** of the threaded cylinder **B 802**.

Embodiment 39: The skate runner of embodiment 34 further comprising an attachment plate **665/675** that possess a convex surface that conforms to the concave lift ring top surface **902**, the attachment plate **665/675** configured to attach to a sole **680** of an ice-skate boot **699**.

Embodiment 40: The skate runner of embodiment 39 further comprising a washer **668** that fits in an accommodating washer recess **666** in the convex surface of the attachment plate **665/675**, the washer **668** receives a threaded bolt **672** that screws into a threaded/tapped hole **B 825** in the side/side dovetail module **800**, the threaded bolt **672** secures the washer **668**, the attachment plate **665/675** and the lift ring **900** to the side/side dovetail module **800**.

Embodiment 41: The skate runner of embodiment 40 wherein the threaded bolt **672** attaches a boot sole to the side/side dovetail module **800**, the boot sole interposed between a bolt head of the threaded bolt.

35

Embodiment 42: The skate runner of embodiment 37 wherein the threaded ring A **720**, the threaded ring B **740** and the threaded ring C **820** possess grips **722**.

The embodiment list (the enumerated embodiments) is not exhaustive of the embodiments presented throughout the description, but rather are merely one example of a contemplated embodiment chain consistent with embodiments of the present invention. In other words, there are numerous other embodiments describe herein that are not in the embodiment list.

It is to be understood that even though numerous characteristics and advantages of various embodiments of the present invention have been set forth in the foregoing description, together with the details of the structure and function of various embodiments of the invention, this disclosure is illustrative only, and changes may be made in detail, especially in matters of structure and arrangement of parts within the principles of the present invention to the full extent indicated by the broad general meaning of the terms in which the appended embodiments are expressed. For example, each element can stand alone to adjust solely for the degree of freedom desired without departing from the scope and spirit of the present invention. Likewise, less than all of the adjustable components can be combined to provide several degrees of freedom presented within this disclosure while still maintaining substantially the same functionality without departing from the scope and spirit of the present invention. Moreover, other mechanical elements can be implemented to accomplish the degree of freedom adjustments presented within this disclosure while still maintaining substantially the same functionality without departing from the scope and spirit of the present invention. Another example can include using other mechanical arrangements that fulfill the same functionality as dovetails and cooperating channels without departing from the scope and spirit of the present invention. Furthermore, embodiments envision the dovetail channels essentially being replaced with dovetails and the dovetails being replaced with the dovetail channels so long as their mating relationships remain intact. The threaded cylinders and threaded rings can be used on either side of the dovetail channels/dovetail relationships. These inversions maintain the same functionality without departing from the scope and spirit of the present invention. Finally, although the preferred embodiments described herein are directed to hockey skates, it will be appreciated by those skilled in the art that the teachings of the present invention can be applied to other systems (such as figure skates, roller blades and speed skates, for example), without departing from the spirit and scope of the present invention.

It will be clear that the present invention is well adapted to attain the ends and advantages mentioned as well as those inherent therein. While presently preferred embodiments have been described for purposes of this disclosure, numerous changes may be made which readily suggest themselves to those skilled in the art and which are encompassed in the spirit of the invention disclosed and as defined in the appended claims.

What is claimed is:

1. A skate riser system comprising:
a riser defined between a boot adapter mount end and a
skate runner mount end, the riser is not adjustable;
a boot adapter mount connected to the boot adapter mount
end, the boot adapter mount configured to connect to a
boot sole of a skate boot;
a quick release shaft extending into a riser aperture in the
riser between the ends; and

36

the quick release shaft comprising a key retaining a skate runner mount to the riser when in a first position but not when in a second position,

wherein the skate runner mount comprises a retaining block that extends into the riser at the skate runner mount end, a shaft retention channel in the retaining block cooperates with the quick release shaft.

2. The skate riser system of claim 1, wherein the riser comprises a sleeve that extends from at least one riser side of the riser, the sleeve accommodates the quick release shaft axially along the sleeve.

3. The skate riser system of claim 2, wherein the sleeve is cylindrical.

4. The skate riser system of claim 1, wherein the key is a narrowing slot in a portion of the quick release shaft that when rotated in the first position is not captured by the shaft retention channel but when rotated in the second position is captured by the shaft retention channel.

5. The skate riser system of claim 1, wherein when the quick release shaft is rotated in the first position, the riser is not fixedly attached to the skate runner mount but when the quick release shaft is rotated in the second position, the riser is fixedly attached to the skate runner mount.

6. The skate riser system of claim 1, wherein the quick release shaft is cylindrical and the shaft retention channel conforms to the quick release shaft, the shaft retention channel comprising a semicircular cross section that is between 210 degrees and 320 degrees.

7. The skate riser system of claim 1, wherein the riser is a side offset riser that shifts a skate blade to the left or right of a sole midplane that extends vertically along a neutral axis of the boot sole.

8. The skate riser system of claim 1, wherein the skate runner mount is a fore/aft offset skate runner mount that shifts a skate blade towards a heel end or toe end of the skate boot.

9. The skate riser system of claim 1, wherein the riser has a different Z-height than a second riser.

10. The skate riser system of claim 1, wherein the skate runner mount comprises an arc shaped skate runner interface configured to rotate the boot sole out from a sole midplane that extends vertically along a neutral axis of the boot sole.

11. A skate riser and quick release apparatus comprising:
a static riser comprising a boot adapter mount configured
to attach to a boot sole;
a skate runner mount extending from a skate runner; and
the skate runner mount removably connected to the static
riser via a quick release shaft that extends through the
skate runner mount and at least a portion of the static
riser,
wherein the skate runner mount is adjustably attached to
the skate runner in a neutral, pronate or supinate
relationship.

12. The skate riser and quick release apparatus claim 11,
wherein the skate runner is connected to either an ice-skate
blade or a plurality of roller-blade wheels.

13. The skate riser and quick release apparatus claim 11,
wherein the static riser comprises a different side offset
and/or a different Z-height than a second static riser, wherein
the side offset riser shifts a skate blade to the left or right of
a sole midplane that extends vertically along a neutral axis
of the boot sole.

14. The skate riser and quick release apparatus claim 11,
wherein the quick release shaft comprises a key that when
rotated in an unlocked position from a locked position, the
skate runner mount is disengaged from the static riser.

15. A method for disengaging a skate runner from a skate boot, the method comprising:

providing a riser comprising a boot adapter mount configured to attach to a boot sole, a skate runner mount extending from a skate runner; 5

engaging a retaining extension that extends from the skate runner mount in an overlapping relationship with the riser, wherein when in the overlapping relationship a runner mount retaining channel of the retaining extension aligns with a riser channel of the riser; 10

locking the retaining extension to the riser via a quick release shaft that extends through the riser channel and the runner mount retaining channel; and

unlocking the retaining extension from the riser by rotating the quick release shaft in an unlocked orientation 15 while the quick release shaft remains extended through the riser channel and the runner mount retaining channel.

16. The method of claim **15**, wherein the retaining extension is a retaining block that extends into a riser cavity of the 20 riser, and the riser channel captures the quick release shaft from disengaging from the riser.

17. The method of claim **15**, wherein the locking step is accomplished via a key in the quick release shaft when the quick release shaft is rotated in a locking orientation and 25 wherein an unlocking step is accomplished by disengaging the skate runner from the boot sole by unlocking the retaining extension from the riser by rotating the quick release shaft in an unlocking orientation.
